RAILWAY TRAFFIC CONTROLLING
APPARATUS

Ralph R. Kemmerer, Swissvale, Pa., assignor to
The Union Switch & Signal Company, Swiss-
vale, Pa., a corporation of Pennsylvania

Application May 11, 1940, Serial No. 334,610

15 Claims.

(Cl. 246—63)

My invention relates to railway traffic controlling apparatus, and it has particular reference to the organization of such apparatus into railway signaling systems of the class wherein coded trackway energy is utilized to control either or both wayside signals and train-carried cab signals.

It has been proposed heretofore in code signaling systems utilizing trackway energy of the frequency code type, to employ a plurality of distinctive code frequencies or rates one for each of the several indications to be controlled or displayed. Such systems also employ a plurality of code distinguishing or decoding units one for each of the different rates of coding but one, with the result that as the number of individual frequencies employed is increased in order to obtain an increased number of signal controls or indications, a corresponding increase must be made in the number of decoding units employed. This has limited to a considerable extent the number of indications provided by both the wayside and cab signal equipment, since it has been thought inadvisable to employ too numerous decoding units because of their relatively large cost of manufacture. In addition, the number of code frequencies available practicable for use is somewhat limited since relatively high rate codes are unsatisfactory because of the necessity of constructing code following relays which mechanically follow each individual code period. As a result of the factors mentioned above, it has been thought advisable to limit code wayside and cab signaling systems to but relatively few indications, thereby requiring the use of only a few individual code rates.

In view of the above-mentioned and other important considerations, it is an object of my present invention to provide novel and improved railway traffic controlling apparatus wherewith an increased number of controls may be effected through the medium of the customary few individual code rates.

Another object of my invention is the provision of railway traffic controlling apparatus incorporating novel and improved means selectively operated by each of a plurality of distinctive codes of trackway energy constituted by coding the supply of such energy either individually at one or another of the customary few code rates or in combinations of two of such code rates repeated alternately.

A further object of my invention is to incorporate such code responsive means into railway traffic controlling apparatus in such manner that

each distinctive combination of two code rates is utilized to control a less restrictive function than is controlled by either of its two component codes, whereby a failure to such apparatus properly to respond to a combined code effects the control of a more restrictive function than is controlled by such combined code.

An additional object of my invention is the further organization of such code responsive means into railway traffic controlling apparatus in such manner that the particular function controlled by each distinctive code may be varied by manually operable means, thereby enabling different classes of trains to be controlled in different manners.

A still further object of my invention is the provision of novel and improved means controlled by traffic conditions in a section for modifying or changing the code supplied to the rails of the section.

Another object of my invention is the organization of railway traffic controlling apparatus into novel and improved forms of railway signaling systems.

The above-mentioned objects, as well as other important objects and characteristic features of my invention which will become readily apparent from the following description, are attained by supplying to the rails of a trackway one or another of a plurality of different codes each of which is constituted by coding the supply of trackway energy either at one or another of the usual code rates individually or at first one and then another of two of such code rates alternately. In addition, railway traffic controlling apparatus is employed in which a plurality of code distinguishing or decoding units, one for each of the different individual rates of coding but one, are provided each with additional means for detecting the component code rates of each combination of two code rates applied alternately, and such additional means and the decoding units cooperate in selectively controlling a train governing device.

The invention further consists in the parts and in the arrangement and organization of such parts into railway signaling systems, as well be described more fully hereinafter.

I shall describe a few forms of apparatus embodying my invention, and shall then point out the novel features thereof in claims.

In the accompanying drawings,

Fig. 1 is a line diagram illustrating a stretch of railway track and the manner in which wayside signals associated with such stretch may be

controlled by apparatus embodying my invention.

Fig. 2 is a diagrammatic view illustrating a preferred form of trackway apparatus embodying my invention when provided for a typical one of the sections represented in Fig. 1.

Fig. 3 is a diagrammatic representation of several different individual and combined codes which may be supplied to the trackway by the apparatus shown in Fig. 2.

Fig. 4 is a chart showing the conditions assumed by each decoding relay of the group shown in Fig. 2 under the several code conditions; the aspects displayed by the signals represented in Fig. 1 for each code condition; and also the manner in which the codes represented in Fig. 3 are distributed in the sections in the rear of an occupied section for providing a six-block, seven-indication signal system embodying my invention.

Fig. 5 is a diagrammatic view illustrating a preferred form of train-carried apparatus embodying my invention and adapted for use in connection with a trackway provided with trackway apparatus of the type shown in Fig. 2.

Fig. 6 is a graphical representation showing typical braking-distance curves for each of three different classes of trains.

Fig. 7 is a diagrammatic view illustrating a modified form of the apparatus shown in Fig. 5, and also embodying my invention.

Fig. 8 is a chart showing the manner in which the selecting means of Fig. 7 controls the aspects displayed by the cab signal under the different code conditions.

Fig. 9 is a diagrammatic view illustrating another modified form of the apparatus shown in Fig. 2, and also embodying my invention.

Figs. 10a and 10b, when placed end to end with Fig. 10a on the left, constitute a diagrammatic view illustrating a further modified form of the apparatus shown in Fig. 2, and also embodying my invention.

Figs. 11 and 12 are each diagrammatic views illustrating modifications of a portion of the apparatus shown in Figs. 10a and 10b, and each also embodying my invention.

Figs. 13 and 14 are diagrammatic views each showing modified forms of the apparatus illustrated in Figs. 10a and 10b, and which also embody my invention.

Fig. 15 is a diagrammatic view showing a modified form of the apparatus represented in Fig. 14, and also embodying my invention.

Fig. 16 is a diagrammatic view showing another modified form of the apparatus illustrated in Fig. 14, and also embodying my invention.

Fig. 17 is a diagrammatic view which illustrates a preferred form of train-carried apparatus adapted for use in connection with the wayside apparatus represented in Figs. 10a and 10b, 13, 14, 15 or 16, and also embodying my invention.

Similar reference characters refer to similar parts in each of the several views.

Referring first to Fig. 1, the reference character X designates a stretch of railway track over which traffic normally moves in the direction indicated by an arrow, or from left to right as viewed in the drawing. The stretch of track X is divided by means of the usual insulated rail joints, into a plurality of successive adjoining track sections of which seven sections in all are illustrated. Each of the sections represented in Fig. 1 is provided adjacent its entrance end with a multiple indication railway traffic controlling signal, designated by the reference character S

plus a suffix corresponding to its location. These signals are illustrated in Fig. 1 displaying the various distinguishing indications to which they are respectively controlled in response to the presence of a train W in the extreme right-hand section P—Q of the stretch, by apparatus embodying my invention and presently to be described in detail.

The track sections of stretch X are each provided with trackway apparatus of the type required for a combined wayside and cab signal system of the frequency code type, but I shall describe in detail only the trackway apparatus provided for a typical one of such sections since it is assumed that each of the sections is provided with apparatus substantially similar to that shown in Fig. 2 provided for the typical section P—Q. For convenience also, the same reference characters will be used throughout the description of the apparatus to designate those parts of the apparatus associated with other sections that correspond to the parts shown in Fig. 2 associated with section P—Q.

Referring now to Fig. 2, the rails 1 and 1a of the stretch as shown are divided by means of the usual insulated rail joints 2 to form track section P—Q and this section is provided with a track circuit, the rails of which are supplied with trackway energy through the medium of a track transformer TTQ which has its secondary winding 5a connected across such rails adjacent the exit end Q of the section. The primary winding 6a of transformer TTQ is connected with trackway code transmitting means (not shown) located at location Q, whereby as will be pointed out presently in detail, the rails of the section are supplied with one or another of a plurality of codes, which codes are constituted by coding energy supplied to the trackway at one or another of a plurality of code rates individually or at first one and then another of two of such code rates alternately. I shall designate as individual codes those constituted by coding the supply of energy individually at one or another of the plurality of code rates, and shall designate as combination codes those constituted by coding the supply of energy alternately at first one and then another of two of such code rates. For example, it is customary in railway signaling to employ alternating current coded or periodically interrupted at the rates of 75, 120 and 180 times per minute and I shall use by the way of illustration in describing apparatus embodying my invention such code rates as the individual codes. A combination code is constituted by cyclically using at least two of such rates alternately. Thus a combination code would be constituted by supplying current coded at the 180 code rate for a predetermined interval such as two seconds and then coded at the 120 code rate for two seconds and this combination cyclically repeated. As will be made clear presently, the trackway code transmitting means located at signal location Q for supplying energy to primary winding 6a of transformer TTQ is controlled by traffic conditions in advance of section P—Q, and since this apparatus is substantially similar to the trackway code transmitting apparatus located at signal location P for supplying trackway energy to the rails of the section located next in the rear of the section illustrated in Fig. 2, only the transmitting apparatus located at signal location P is shown in the drawing.

The trackway code transmitting apparatus located adjacent signal location P (and in like

manner the similar apparatus located at signal location Q) comprises a suitable source of alternating current, such for example as a generator not shown but having its opposite terminals designated by the reference characters BX and CX, a coding device or transmitter CT having a plurality of continuously operating contact members, and a plurality of circuits controlled by decoding apparatus associated with section P—Q and later to be described in detail, and by means of which circuits energy from the source is supplied to the track rails of the section located in the rear of section P—Q.

The code transmitter CT may be any one of several suitable types and is here shown as being of the type having a motor 8 which is constantly supplied with alternating current so that the transmitter is continuously active. Motor 8 is operatively connected with a rotatable shaft 9, indicated by a dotted line, upon which are secured a plurality of cams 10, 11, 12 and 13. The shaft 9 is arranged to revolve in response to the actuation of motor 8, in a counterclockwise direction at a constant rate, say at 15 revolutions per minute, thereby causing the cams mounted thereon to revolve in a counterclockwise direction. Each of the cams is provided with a different number of teeth or projections, cam 10 being shown provided, for example, with five teeth, cam 11 with eight teeth, cam 12 with twelve teeth, and cam 13 with but one tooth or projection. Transmitter CT further comprises a plurality of code contact members two members 15 of which are associated with cam 10, the arrangement being such that each contact member is actuated by each tooth of the cam to close contacts 15—15a and 15—15b, respectively, and to open such contacts between successive teeth. Similarly, two contact members 120 associated with cam 11 are each actuated by each tooth of cam 11 and each closes a contact 120—120a and 120—120b, respectively, which contacts are opened between successive teeth of the cam. Cam 12 also is provided with a contact member 180 which is engaged by each tooth of the cam to close a contact 180—180a, this contact being opened between successive teeth. Cam 13 is provided with two contact members 15 which are engaged respectively by the single projection on the cam to each close a contact 15—15a or 15—15b, respectively, and which members each close another contact 15—15c or 15—15d, respectively, whenever such members ride on the low or unprojecting portion of the cam. It follows, therefore, that with the shaft of device CT revolving at a constant rate of 15 revolutions per minute contact 15—15a or 15—15b when interposed in a circuit supplied with current periodically interrupts or codes such current at the rate of 75 times per minute. This coding is illustrated by the 75 code curve of Fig. 3, the raised portions of the curve representing the "on" periods during which current flows in the circuit and the depressed portions of the curve representing the "off" periods during which no current flows. The time interval of each "on" and "off" period of this 75 code is substantially equal to $\frac{1}{75}$ of a second.

The 120 code curve of Fig. 3 illustrates in a similar manner the current flowing in a circuit in which is interposed contact 120—120a or 120—120b, each "on" and "off" period of this latter code being substantially equal to $\frac{1}{4}$ of a second. Likewise, the 180 code curve of Fig. 3 represents the current flowing in a circuit hav-

ing interposed therein contact 180—180a, the "on" and "off" periods of such code being substantially $\frac{1}{6}$ of a second. The purpose of the contacts associated with cam 13, each of which contacts is closed for a two seconds interval, will be made clear presently.

The track circuit of section P—Q further includes a code responsive track relay TR, which relay is connected through the medium of a relay transformer RT and a rectifier RX to receive energy from the rails I and Ia at the entrance end P of section P—Q. The winding of relay TR is connected across the output terminals of rectifier RX; the input terminals of this rectifier are connected to the secondary winding of transformer RT; and the primary winding of this transformer is connected across the rails of section P—Q adjacent entrance end P of the section.

The decoding means previously referred to as being provided at signal location P (see Fig. 2) comprises a decoding transformer DT, a code detecting relay H, two decoding units DU—120 and DU—180, two code selecting relays BJ and AJ and three repeater relays associated with each of the code selecting relays.

The decoding transformer DT comprises the usual center-tapped primary winding 18 having a first portion thereof supplied through front contact 20 of relay TR with unidirectional current which flows from a suitable source, such as a battery not shown but having its opposite terminals designated by the reference characters B and C, in one direction in the first portion of the winding and supplied through back contact 21 of relay TR with unidirectional current flowing in the other direction in the second portion of the winding. In this manner is simulated the action of alternating current having a frequency equal to the rate at which relay TR is responding to coded current received from the rails of the section. Transformer DT further comprises a center-tapped secondary winding 19 connected to code detecting relay H through the medium of front and back contacts 22 and 23, respectively, of relay TR in such manner as to rectify the alternating current induced in winding 19 into and supply relay H with substantially unidirectional current. The relay H is a direct current relay arranged and proportioned to be picked up whenever relay TR is following coded energy received from the rails of the section, hence such relay functions to detect whether or not relay TR is following code.

The decoding transformer DT also supplies energy to relays AJ and BJ through the medium of decoding units DU—180 and DU—120 respectively. The details of construction of the decoding units DU—180 and DU—120 are not shown in the drawing, but these units usually comprise a rectifier and a reactor condenser tuning unit tuned to resonance at a frequency corresponding to the 180 and to the 120 code, respectively, thereby relay AJ is effectively energized and picked up when and only when relay TR is following 180 code, and relay BJ is effectively energized when and only when relay TR is following 120 code. Preferably, the connection of decoding unit DU—120 with relay BJ includes a back contact 24 of relay AJ, thereby insuring that relay BJ will be released when relay AJ is picked up in response to 180 code.

The three repeater relays associated with relay AJ include two slow release repeater relays AJP1 and AJP2, each proportioned to have a

slow release period slightly longer than two seconds in duration, and a third repeater relay AJPS. The first slow release repeater relay AJP1 is energized over an obvious circuit controlled by front contact 25 of relay AJ and hence functions as an ordinary slow release repeater, being energized whenever relay AJ is constantly picked up or whenever relay AJ is picked up and released for alternate two second intervals. The second slow release relay AJP2 is energized over an obvious circuit controlled by back contact 26 of relay AJ and front contact 27 of repeater relay AJP1 and hence functions to detect whether relay AJ is alternately being picked up and released for two-second intervals. The third repeater relay AJPS is provided with a pick-up circuit which may be traced from terminal B through front contact 28 of relay AJ, front contact 29 of relay AJP1, front contact 30 of relay AJP2, and the winding of relays AJPS to terminal C. Relays AJPS also is provided with a stick circuit, in which latter circuit its own front contact 31 closes a shunt path around front contact 28 of relay AJ interposed in its pick-up circuit just traced.

Relay BJ controls two slow release relays BJP1 and BJP2, each provided with a slow releasing period slightly in excess of two seconds, and another or a third repeater relay BJPS. The first slow release relay BJP1 is energized over an obvious circuit including front contact 32 of relay BJ and thus repeats relay BJ in a manner similar to the manner pointed out that relay AJP1 repeats relay AJ. The second slow release repeater relay BJP2 is controlled over an obvious circuit including back contact 33 of relay BJ and front contact 34 of relay BJP1, thereby detecting if relay BJ is being picked up and released alternately for intervals each two seconds in duration. The third repeater relay BJPS is provided with a pick-up circuit including the source of current, front contact 35 of relay BJ, front contact 36 of relay BJP1, front contact 37 of relay BJP2, and the winding of relay BJPS. The latter relay also is provided with a stick circuit in which its own front contact 38 closes a shunt path around front contact 35 of relay BJ in the previously traced pick-up circuit of the relay.

The decoding apparatus above described functions to selectively control, in a manner to be pointed out in detail presently, the wayside signal provided for the associated track section. Such signal may take any one of many well-known forms of railway signaling devices, but is shown in Fig. 2 (see signal SP) for the sake of illustration as comprising three individual color light units disposed one above the other on the associated signal mast. Each of the units, which I shall refer to as units U1, U2 and U3 in accordance with their respective positions on the signal mast with unit U1 located at the top of the mast, comprises a red lamp R, a yellow Y and a green lamp G.

The decoding apparatus further cooperates with its associated code transmitter CT to selectively control in accordance with traffic conditions, the supply of trackway energy to the track rails of the section next in the rear. The manner in which the control of the associated signal and the supply of trackway energy to the rails of the section next in the rear are effected by apparatus embodying my invention will best be understood from the following description of the operation of the apparatus as a

whole. In such description, the apparatus represented in Fig. 2 will be assumed to correspond to the similar apparatus provided for each of the sections represented in Fig. 1, and the operation of the apparatus as a whole will be described by tracing in Fig. 2 the various circuits that are set up by such or corresponding apparatus in response to each of the different code conditions in the trackway. To facilitate this description, reference will also be made to Fig. 4 wherein there is set forth in chart form the various codes received and sent (columns f and g, respectively, of Fig. 4), by the wayside apparatus at each signal location; the aspects displayed by each unit of the various signals (columns b, c and d of Fig. 4); the positions assumed by each of the various relays comprising the decoding apparatus located at the several signal locations (columns j to p, inclusive); and the meaning of the various aspects displayed by the signals (column e).

As can be seen in Fig. 1, section P—Q is occupied by a train W so that trackway energy is shunted away from the track relay of such section. From column f of Fig. 4, it can be seen that the apparatus at signal SP receives no code, and columns j through p, inclusive, of Fig. 4 indicate that all decoding relays are released; the released and picked-up positions of the decoding relays being indicated in Fig. 4 by representing the armatures associated with such relays in a dropped-away or picked-up position, respectively. Also, it can be seen that each unit of signal SP displays its red aspect (see columns b, c and d of Fig. 4) and that 75 code (see column g of Fig. 4) is transmitted to the next section to the rear.

Referring now to Fig. 2, the wayside apparatus there illustrated is shown in the condition responsive to a train W occupying its associated section. In this condition of the apparatus, relay TR is inactive and all of the decoding relays are released as shown in Fig. 2 and as set forth in the table of Fig. 4.

With the decoding relays located at signal location P all released, lamp R of unit U1 of signal SP is provided with an energizing circuit which may be traced from terminal B through back contact 40 of relay H and the filament of lamp R of unit U1 to terminal C. Lamp R of unit U2 of signal SP likewise is provided with an energizing circuit passing from terminal B through back contact 41 of relay H and the filament of lamp R of unit U2 to terminal C; and similarly lamp R of unit U3 of the signal is provided with an energizing circuit passing from terminal B through back contact 42 of relay H and the filament of lamp R of unit U3 to terminal C. It follows, therefore, that each unit of signal SP displays its red aspect, which denotes that its associated section P—Q is occupied by a train.

Also, a circuit is completed for supplying 75 code trackway energy to the rails of the section next to the rear of section P—Q, that is, section O—P. This circuit may be traced from terminal BX through contact 75—75a of transmitter CT, back contact 43 of relay H and primary winding 6 of transformer TT, which transformer has its secondary winding 5 connected across the track rails of the section next in the rear, to terminal CX.

When 75 code is supplied to the rails of section O—P, relay TR associated with that section is operated at this rate and its associated relay H

is energized (see column *j* of Fig. 4, but all other decoding relays are released. The energization of relay H establishes a circuit for lamp Y of unit U3 of signal SO, which circuit may be traced in Fig. 2 from terminal B through front contact 44 of relay H, back contact 45 of relay AJP1 and the filament of lamp Y of unit U3 to terminal C. Unit U1 of signal SO now is caused to display its red aspect over a circuit which may be traced from terminal B through front contact 54 of relay H, back contact 46 of relay AJPS, back contact 47 of relay AJP1, back contact 48 of relay BJPS and the filament of lamp R of unit U1 to terminal C. Also, unit U2 of signal SO is caused to display its red aspect over a circuit passing from terminal B through front contact 49 of relay H, back contact 50 of relay AJPS, back contact 51 of relay AJP1, back contact 52 of relay BJPS, back contact 53 of relay BJP1 and the filament of lamp R of unit U2 to terminal C. Signal SO therefore displays a "red" over "red" over "yellow" aspect, which indicates that one clear block intervenes between the signal and the next occupied block. In addition, with relay H picked up, 120 code trackway energy is supplied to the section N—O over a circuit which may be traced from terminal BX through contact 120—120a of transmitter CT, back contact 55 of relay BJP1, back contact 56 of relay BJPS, back contact 57 of relay AJP1, back contact 58 of relay AJPS, front contact 59 of relay H and primary winding 6 of transformer TT to terminal CX.

The 120 code supplied to section N—O causes the track relay of section N—O to operate at a corresponding rate and as a result relays H, BJ and BJP1 associated with signal SN of that section are picked up (see columns *j* and *p* of Fig. 4). The picking up of relay BJP1 controls lamp Y of unit U2 of signal SN to its lighted indication over a circuit which may be traced in Fig. 2 from terminal B through front contact 49 of relay H, back contact 50 of relay AJPS, back contact 51 of relay AJP1, back contact 52 of relay BJPS, front contact 60 of relay BJP1 and the filament of lamp Y of unit U2 to terminal C. The energizing circuits for the lamps of units U1 and U3 of signal SN are similar to those previously traced for corresponding units of signal SO, and consequently signal SN displays a "red" over "yellow" over "yellow" aspect, indicating that two blocks are clear between the signal location and the next occupied block. Also, with relays H and BJP1 associated with section N—O picked up, section M—N is supplied with 120—75 code trackway energy by virtue of the action of contacts 15—15b and 15—15d of transmitter CT, these contacts functioning to cause 120 code and 75 code to be supplied alternately for successive intervals each of two seconds in duration. During the intervals that contact 15—15b of transmitter CT is closed, the rails of section M—N are supplied with 120 code over a circuit which extends from terminal BX through contact 120—120b of transmitter CT, front contact 64 of relay BJP1, back contact 56 of relay BJPS, back contact 57 of relay AJP1, back contact 58 of relay AJPS, front contact 59 of relay H, and primary winding 6 of transformer TT to terminal C. Then, during the alternate intervals that transmitter CT closes contact 15—15d, 75 code is supplied to the rails of section M—N over a circuit which extends from terminal BX through contact 75—75b of transmitter CT, contact 15—15d of transmitter

CT, front contact 64 of relay BJP1, and then passing from contact 64 of relay BJP1 through the circuit corresponding to the circuit just traced from such contact for 120 code. Curve 5 120—75 of Fig. 3 represents the current flow in the above circuits by means of which 120 and 75 code are recurrently supplied for alternate intervals of two seconds each to the rails of section M—N to provide a 120—75 combined code.

10 In response to the 120—75 code supplied to section M—N, decoding relays H, BJP1, BJP2 and BJPS associated with section M—N are energized (see table Fig. 4). Relay H of section M—N is energized by virtue of relay TR of that section 15 following code. Relay BJ is energized during the alternate intervals of two seconds that relay TR follows 120 code and is released during the intervals that relay TR follows 75 code. Relay BJP1 is energized during each interval that relay 20 BJ is picked up, and by virtue of its slow releasing characteristics, relay BJP1 remains picked up to hold its front contacts closed during the two-second intervals that relay TR follows 75 code and relay BJ is released. Relay BJP2 is 25 energized over front contact 34 of relay BJP1 during each two-second interval that relay BJ is released, and the slow releasing characteristics of relay BJP2 function to hold its armature picked up during the alternate intervals that relay BJ is picked up. Relay BJP2 becomes picked up over its previously traced pick-up circuit after 30 relays BJ, BJP1 and BJP2 pick up; and relay BJPS is held up over its stick circuit as long as relay BJ is alternately picked up and released to maintain both relays BJP1 and BJP2 energized.

With the decoding apparatus located at signal SM responding in the above described manner to the combined 120—75 code, each unit of signal SM is controlled to display its yellow aspect. Lamp Y of unit U1 of signal SM is energized over a circuit which may be traced in Fig. 2 from terminal B through front contact 54 of relay H, back contact 46 of relay AJPS, back contact 47 of relay AJP1, front contact 62 of relay BJPS and the filament of lamp Y of unit U1 to terminal C. Lamp Y of unit U2 of signal SM is energized over a circuit which extends from terminal B through front contact 49 of relay H, back contact 50 of relay AJPS, back contact 51 of relay AJP1, front contact 63 of relay BJPS and the filament of lamp Y of unit U2 to terminal C; and lamp Y of unit U3 is energized over a circuit extending from terminal B through front contact 44 of relay H, back contact 45 of relay AJP1 and the filament of lamp Y of unit U3 to terminal C. Signal SM in displaying a "yellow" over "yellow" over "yellow" aspect indicates that three blocks are clear between the signal and the next occupied block.

In addition, the decoding apparatus located at signal SM causes 180 code to be supplied to the rails of the next adjacent section to the rear, section L—M. This energy is supplied over a circuit extending from terminal BX through contact 180—180a of transmitter CT, front contact 65 of relay BJPS, back contact 57 of relay AJP1, back contact 58 of relay AJPS, front contact 59 of relay H and primary winding 6 of transformer TT to terminal CX.

In response to the supply of 180 code to section L—M, relays H, AJ and AJP1 located at signal location SL are picked up. It should be noted that relay BJ cannot respond to 180 code inasmuch as its energizing circuit is open at back

contact 24 of relay AJ. With relays H, AJ and AJP1 energized, lamp G of unit U3 of signal SL is illuminated over a circuit which may be traced in Fig. 2 from terminal B through front contact 44 of relay H, front contact 66 of relay AJP1, and the filament of lamp G of unit U3 to terminal C. Lamps Y of units U1 and U2 of signal SL also are illuminated, the circuit for lamp Y of unit U1 passing from terminal B through front contact 54 of relay H, back contact 46 of relay AJPS, front contact 67 of relay AJP1 and the filament of lamp Y of unit U1 to terminal C; and the circuit for lamp Y of unit U2 extending from terminal B through front contact 49 of relay H, back contact 50 of relay AJPS, front contact 68 of relay AJP1 and the filament of lamp Y of unit U2 to terminal C. Signal SL thus displays a "yellow" over "yellow" over "green" aspect, indicating the presence of four clear blocks between the signal and the next occupied block.

Section K—L located next in the rear of section L—M is supplied with trackway energy formed into a code combination comprising alternate two-second intervals of 180 and 75 code, by circuits established by the decoding apparatus associated with section L—M. 180 code is supplied to the rails of section K—L during the alternate intervals each of two seconds in duration that contact 15a—15 of coder CT is closed and a circuit is completed from terminal BX through contact 180—180a of transmitter CT, contact 15a—15 of transmitter CT, front contact 70 of relay AJP1, back contact 58 of relay AJPS, front contact 59 of relay H and primary winding 6 of transformer TT to terminal CX. 75 code is supplied to the rails of section K—L during the other two-second intervals that contact 15—15c of transmitter CT is closed and contact 15a—15 of transmitter CT is opened, over a circuit extending from terminal BX through contact 75—75a of transmitter CT, back contact 71 of relay AJPS, contact 15c—15 of transmitter CT, front contact 70 of relay AJP1, back contact 58 of relay AJPS, front contact 59 of relay H, and primary winding 6 of transformer TT to terminal CX. Curve 180—75 of Fig. 3 represents the current supplied to section K—L over the circuits just traced for this combination code.

The supply of 180—75 code to the rails of section K—L causes decoding relays H, AJ, AJP1, AJP2 and AJPS associated with that section to be picked up. Relay H of section K—L is picked up in response to relay TR following code; relay AJ is energized during the alternate two-second intervals that relay TR responds to 180 code and is deenergized during the intervals that relay TR follows 75 code; relay AJP1 is energized during each two-second interval that relay AJ is picked up and relay AJP1 remains picked up by virtue of its slow releasing characteristics during the alternate intervals that relay AJ is released; relay AJP2 is energized over front contact 27 of relay AJP1 during each two-second interval that relay AJ is released, and the slow releasing characteristics of relay AJP2 maintain that relay picked up during the alternate picked-up periods of relay AJ; and relay AJPS picks up to complete its stick circuit after both relays AJP1 and AJP2 become picked up in response to the alternate picking up and releasing of relay AJ.

Signal SK is controlled to display a "yellow" over "green" over "green" aspect, thereby indicating five clear blocks between the signal and the next occupied block, by virtue of the response of the decoding apparatus located at signal loca-

tion SK to the combined 180—75 code. The decoding apparatus located at signal SK controls that signal to display the above-mentioned aspect by illuminating lamp Y of unit U1 over a circuit which may be traced in Fig. 2 from terminal B through front contact 54 of relay H, front contact 72 of relay AJPS, back contact 73 of relay BJPS and the filament of lamp Y of unit U1 to terminal C; by setting up a circuit including front contact 49 of relay H, front contact 74 of relay AJPS and the filament of lamp G of unit U2 whereby that lamp is illuminated; and by completing a circuit including front contact 44 of relay H, front contact 66 of relay AJP1 and the filament of lamp G of unit U3 of signal SK whereby that lamp is illuminated.

The rails of section J—K are supplied by the decoding apparatus and code transmitter located at signal location SK with trackway energy formed of alternate intervals of 180 and 120 code. During the intervals that contact 15—15a of transmitter CT is closed, the rails of section J—K are supplied with 180 code over a circuit which extends from terminal BX through contact 180—180a of transmitter CT, contact 15a—15 of transmitter CT, front contact 77 of relay AJPS, front contact 59 of relay H and primary winding 6 of transformer TT to terminal CX. Then, during the alternate intervals of two seconds each that contact 15—15c of transmitter CT is closed, the rails of section J—K are supplied with 120 code over a circuit extending from terminal BX through contact 120—120a of transmitter CT, front contact 78 of relay AJPS, contact 15c—15 of transmitter CT, front contact 77 of relay AJPS, front contact 59 of relay H and primary winding 6 of transformer TT to terminal CX. The current flowing in the rails of section J—K by virtue of the above-mentioned circuits is represented by the combination code curve 180—120 of Fig. 3.

In response to the supply of 180—120 code to the rails of section J—K, all the decoding relays located at signal location SJ are picked up and each unit of signal SJ is caused to exhibit its green aspect (see table of Fig. 4). Relay H associated with section J—K is picked up in response to the associated track relay following the combined 180—120 code, and relays AJ and BJ are picked up and released, respectively, during the two-second intervals that the track relay responds to 180 code and such relays are released and picked up, respectively, during the alternate two-second intervals that the track relay follows 120 code. The repeater relays AJP1, AJP2, AJPS, BJP1, BJP2 and BJPS accordingly are all energized and are picked up in response to the alternate picking up and releasing of the two code selecting relays AJ and BJ caused by the track relay following the combined 180—120 code. With all the decoding relays associated with section J—K picked up, lamp G of unit U1 of signal SJ is energized over a circuit which may be traced in Fig. 2 from terminal B through front contact 54 of relay H, front contact 72 of relay AJPS, front contact 79 of relay BJPS and the filament of lamp G of unit U1 to terminal C; and lamps G of units U2 and U3 of signal SJ are energized over circuits corresponding to the circuits previously traced for corresponding lamps of signal SK.

In addition, the apparatus located at signal location SJ causes trackway energy of 180—120 code to be supplied to the section next in the rear, over circuits controlled by the decoding

apparatus located at signal location SJ and corresponding to the circuits previously traced for supplying similar trackway energy to the rails of section J—K.

From the foregoing description of the operation of the apparatus embodying my invention, it is readily apparent that I have provided a novel and improved six-block, seven-indication wayside signal system selectively controlled by trackway current requiring only the customary few code rates. An advantage of traffic controlling apparatus embodying my invention is that such apparatus utilizes distinctive codes of trackway energy constituted by coding the supply of such energy either individually at one or another of the customary few code rates or alternately at first one and then another of two of such code rates, whereby the number of indications that can be selectively controlled by coded trackway energy is increased without requiring an increase in the number of individual code rates.

It is also apparent from the foregoing description of the apparatus embodying my invention that the code combinations are utilized to control less restrictive aspects than are controlled by either of the component codes of such combination. Thus, for example, the 75, 120 or 180 codes when supplied individually are utilized to control more restrictive aspects than are controlled by code combinations in which such individual codes are employed. It follows, therefore, that if the apparatus embodying my invention fails to operate properly in response to a code combination and "sticks" on one of the component codes, that is, responds to such one component code but fails to respond to the other component code, such failure will cause the apparatus to effect the control of the aspect associated with the one component code, which aspect as pointed out heretofore is more restrictive than the aspect controlled by the code combination. It can be seen, therefore, that the apparatus embodying my invention incorporates the usual safety features necessary in railway signaling, in that a failure of the apparatus to respond properly to the control energy causes a more restrictive indication to be displayed than is controlled by such control energy.

A further advantage of the apparatus embodying my invention is that a minimum of apparatus is required to modify the apparatus ordinarily employed in the well-known three-block four-indication signal system using three code rates, to selectively respond to a plurality of distinctive code combinations each of which is constituted by a selected two of such individual code rates repeated alternately.

In connection with the wayside signaling apparatus heretofore described, my invention also contemplates the provision of a six-block, seven-indication cab signaling system in which only the customary few individual code rates are utilized either individually or componently as portions of distinctive code combinations formed by alternately supplying energy coded at first one and then another of two of such individual code rates, to selectively control a multiple indication cab signal indicator.

Referring now to Fig. 5, the train-carried cab signaling equipment illustrated is substantially similar to the wayside apparatus shown in Fig. 2, except that in Fig. 5 a train-carried master code following relay MR replaces track relay TR of Fig. 2. The master relay MR is supplied

with trackway energy from the track rails 1 and 1a through the medium of two coils 85 and 86 located in advance of the first pair of locomotive wheels and disposed in inductive relationship with the two track rails, as is the customary practice. The two coils 85 and 86 are connected in series in such manner that when electromotive forces are induced therein by alternating current flowing in the two rails in opposite instantaneous directions, such forces are additive, and the two coils are connected to relay MR through the medium of an amplifier AM which is shown conventionally for the sake of simplicity since it may take any one of many well-known types.

In accordance with the rate at which energy received by relay MR is coded, the relay selectively controls a code detecting relay H and two code selecting relays AJ and BJ, and each of the latter relays AJ and BJ in turn controls three repeater relays, in a manner and by apparatus and circuits which are similar to those pointed out in detail in connection with the apparatus of Fig. 2.

The decoding apparatus carried by the train may be utilized to control any suitable train-carried governing device such, for example, as a cab signal indicator CS, which as shown comprises seven distinctive signal indication units. Suitable acknowledging means, comprising the usual audible indicator AK controlled by a magnet valve MV, is provided to furnish an auxiliary audible indication whenever a change occurs in the indication displayed by indicator CS. Magnet valve MV is controlled through the medium of an acknowledging switch AS and the usual acknowledging relays, which are shown as two-winding relays CU2P, CU3P, CU4P, CU5P, CU6P and CU7P.

It is believed that the manner in which the cab signaling apparatus embodying my invention functions to control indicators CS and AK can best be understood by describing its operation in response to each of the various codes of current received by the apparatus from the track rails.

In describing the operation of the apparatus of Fig. 5, I shall assume that a train operating on track X is provided with cab signaling apparatus heretofore described and embodying my invention. I shall assume also that under the traffic conditions represented in Fig. 1, that is, with train W occupying section P—Q, the train provided with my cab signaling apparatus enters section J—K.

As was explained hereinbefore, section J—K is supplied with 180—120 code when section P—Q is occupied and the intervening sections are unoccupied, so that master relay MR carried by the train in section J—K responds to the code combination formed of 180 and 120 code trackway energy repeated alternately. In view of the fact that the train-carried apparatus embodying my invention is similar to the wayside apparatus previously described, such train-carried apparatus accordingly responds to trackway energy in a manner similar to that in which the decoding apparatus associated with the trackway and illustrated in Fig. 2 responds, so that the table set forth in Fig. 4 applies as well to the train-carried apparatus and indicates the position assumed by each of the decoding relays carried by the train under each condition of trackway code received by the master relay. By consulting the table set forth in Fig. 4, it is apparent that when

relay MR responds to 180-120 code, all of the decoding relays carried by the train are picked up. This is the condition in which the train-carried apparatus is illustrated in Fig. 5, and in this condition of the apparatus indication unit CU1 of cab signal CS is illuminated over a circuit which may be traced from terminal B through front contact 87 of relay H, front contact 88 of relay AJPS, front contact 89 of relay BJPS, the filament of indication unit CU1 of indicator CS, front contact 90 of relay BJPS, front contact 91 of relay AJPS, and front contact 92 of relay H to terminal C. Unit CU1 when illuminated indicates that five blocks, at least, are unoccupied in advance of the section being traversed by the train.

In the normal condition of the apparatus illustrated, all acknowledging relays are released and as a result magnet valve MV is energized over a circuit corresponding to the circuit just traced for unit CU1 up to that unit and then leaving that circuit to pass through back contact 93 of relay CU2P, back contact 94 of relay CU3P, back contact 95 of relay CU4P, back contact 96 of relay CU5P, back contact 97 of relay CU6P, back contact 98 of relay CU7P, contact 108-107 of acknowledging switch AS, the winding of magnet valve MV, back contact 99 of relay CU2P, back contact 100 of relay CU3P, back contact 101 of relay CU4P, back contact 102 of relay CU5P, back contact 103 of relay CU6P and back contact 104 of relay CU7P to rejoin the previously traced circuit of unit CU1 at a point beyond that unit.

If, now, the cab signal equipped train enters section K-L, which is supplied with 180-75 code, then relays H, AJPS, AJP2 and AJP1 are picked up but relays BJ, BJI, BJP2 and BJPS are released (see table of Fig. 4). Indication unit CU2 accordingly becomes illuminated over a circuit which extends from terminal B through front contact 87 of relay H, front contact 88 of relay AJPS, back contact 105 of relay BJPS, the filament of unit CU2, back contact 106 of relay BJPS, front contact 91 of relay AJPS and front contact 92 of relay H to terminal C. The illumination of indication unit CU2 indicates that only four blocks are unoccupied in advance of the section being traversed.

In addition, the release of relay BJPS interrupts the circuit previously traced for magnet valve MV, which accordingly becomes deenergized so that indicator AK provides an audible indication. To silence indicator AK and to acknowledge the changed indication now displayed by the cab signal, acknowledging switch AS may be reversed, whereupon contact 107-108 is opened and contact 109-110 is closed. When contact 109-110 of switch AS closes, the upper windings of each of the acknowledging relays become energized over what I shall term a first pick-up circuit for the acknowledging relays, which circuit may be traced from terminal B through back contact 111 of relay BJPS, contact 109-110 of switch AS, the upper winding of each of the acknowledging relays in multiple (the upper windings of relays CU6P, CU5P, CU4P, CU3P, and CU2P being energized in that sequence in multiple with the upper winding of relay CU1P over front contacts, respectively, of relays CU7P, CU6P, CU5P, CU4P and CU3P), and back contact 112 of relay BJPS to terminal C. When acknowledging relay CU2P picks up, a stick circuit is closed through its own front contacts 113 and 114 for its lower winding, which circuit

corresponds to the circuit previously traced for unit CU2 up to that unit, and then leaves that circuit to pass through front contacts 113 and 114 of relay CU2P, the lower winding of relay

5 CU2P and back contact 112 of relay BJPS to terminal C. Relay CU2P is held energized over its stick circuit until another change is effected in the indication displayed by cab signal CS in response to a change in trackway energy received

10 by the decoding apparatus carried by the train.

If, now, the acknowledging switch AS is restored to its normal position to open contact 109-110, all of the acknowledging relays except relay CU2P are released, and magnet valve

15 MV is reenergized over a circuit path corresponding to the circuit previously traced for unit CU2 up to that unit and then passing through front contact 113 of relay CU2P, back contact 94 of relay CU3P, back contact 95 of relay CU4P, back

20 contact 96 of relay CU5P, back contact 97 of relay CU6P, back contact 98 of relay CU1P, contact 107-108 of switch AS, the winding of magnet valve MV and front contact 115 of relay CU2P to rejoin the circuit of unit CU2 beyond that

25 unit. The energization of magnet valve MV silences indicator AK.

When the cab signal equipped train traverses a section supplied with 180 code, as for example when section L-M is entered, only decoding relays H, AJ and AJP1 are energized (see table of

30 Fig. 4); and indication unit CU3 of cab signal CS is caused to become illuminated over a circuit which extends from terminal B through front contact 87 of relay H, back contact 116 of relay

35 AJPS, front contact 117 of relay AJP1, the filament of unit CU3, front contact 118 of relay AJP1, back contact 119 of relay AJPS and front contact 92 of relay H to terminal C. The illumination of unit CU3 indicates that only three

40 blocks are unoccupied between the block being traversed and an occupied block.

In addition, the release of relay AJPS interrupts the previously traced stick circuit of acknowledging relay CU2P, and also interrupts the 45 previously traced energizing circuit for magnet valve MV. The deenergization of magnet valve MV causes indicator AK to sound. By reversing acknowledging switch AS, the acknowledging relays are sequentially picked up over what I shall

50 term a second pick-up circuit including terminal B, back contact 81 of relay AJPS, contact 109-110 of switch AS, the upper windings of the acknowledging relays in multiple, back contact 80 of relay AJPS or back contact 112 of relay

55 BJPS, and terminal C. Relay CU3P is retained energized over a stick circuit corresponding to the circuit previously traced for unit CU3 up to that unit and then passing through front contacts 83 and 121 of relay CU3P, the lower winding of relay CU3P and back contact 80 of relay AJPS to terminal C. This stick circuit path holds relay CU3P energized until the decoding apparatus carried by the train responds to a different type of trackway energy. With acknowledging relay

60 CU3P picked up, the acknowledging switch AS may be restored to its normal position wherein all of the acknowledging relays except relay CU3P are released and an energizing circuit is established for magnet valve MV over a circuit path

65 connected in multiple with indication unit CU3 and leaving the circuit of that unit before reaching the unit to pass through front contact 83 of relay CU3P, back contacts 95, 96, 97 and 98 of acknowledging relays CU4P, CU5P, CU6P and CU7P, respectively, contact 108-107 of switch AS,

the winding of magnet valve MV, back contact 99 of relay CU2P, and front contact 82 of relay CU3P to rejoin the circuit of unit CU3 beyond that unit. The energization of magnet valve MV silences indicator AK.

In the event that the cab signal equipped train traverses section M—N so that relay MR is supplied with energy of the 120—75 combination code, then relays AJ and AJP1 as well as relays AJP2 and AJPS are released, and relays H, BJ, BJP1, BJP2 and BJPS are energized to control indication unit CU4 of cab signal CS to its illuminated condition over a circuit which extends from terminal B through front contact 87 of relay H, back contact 116 of relay AJPS, back contact 122 of relay AJP1, front contact 123 of relay BJPS, the filament of indication unit CU4, front contact 124 of relay BJPS, back contact 125 of relay AJP1, back contact 119 of relay AJPS, and front contact 92 of relay H to terminal C. The illumination of indication unit CU4 indicates that only two blocks are unoccupied between the section being traversed and an occupied section.

The release of relay AJP1 interrupts the previously traced stick circuit of acknowledging relay CU3P and last-mentioned energizing circuit of magnet valve MV, so that audible indicator AK is caused to sound. If, however, acknowledging switch AS is reversed, then the acknowledging relays become sequentially picked up over their previously traced second pick-up circuit, and a stick circuit is provided for relay CU4P, which circuit corresponds to the energizing circuit of unit CU4 up to that unit and then passes through front contacts 126 and 126a of relay CU4P, the lower winding of relay CU4P and back contact 80 of relay AJPS to terminal C. By restoring acknowledging switch AS to its normal position, all acknowledging relays except relay CU4P are released, and magnet valve MV becomes energized to terminate operation of indicator AK, the magnet valve MV being energized over a circuit path connected in multiple with unit CU4 and leaving the previously traced circuit of that unit at one side of the unit to pass through front contact 126 of relay CU4P, back contacts 96, 97 and 98 of relays CU5P, CU6P and CU1P, respectively, contact 103—107 of switch AS, the winding of magnet valve MV, back contacts 99 and 100 of relays CU2P and CU3P, respectively, and front contact 127 of relay CU4P to rejoin the circuit of unit CU4 on the other side of such unit.

Whenever the train-carried cab signal equipment is responding to 120 code, as for example during the interval that a cab signal equipped train traverses section N—O with section O—P in advance occupied and section O—P unoccupied, then relays BJPS and BJP2 as well as relays AJPS, AJP1, AJP2 and AJ are released and only relays H, BJ and BJP1 are picked up. Indication unit CU5 of the cab signal indicator CS now is caused to be illuminated over a circuit passing from terminal B through front contact 87 of relay H, back contact 116 of relay AJPS, back contact 122 of relay AJP1, back contact 128 of relay BJPS, front contact 129 of relay BJP1, the filament of unit CU5, front contact 130 of relay BJP1, back contact 131 of relay BJPS, back contact 125 of relay AJP1, back contact 119 of relay AJPS and front contact 92 of relay H to terminal C. The illumination of unit CU5 indicates that only one clear block intervenes between the section being traversed and the next occupied section.

In order to silence indicator AK, which was set into operation due to the deenergization of

magnet valve MV and acknowledging relay CU4P when relay BJPS became released, the acknowledging switch AS may be set to its reverse position to complete the previously mentioned pick-up circuit of the acknowledging relays, whereupon all of the acknowledging relays pick up and relay CU5P completes for itself a stick circuit connected in multiple with indication unit CU5 and including its own front contacts 132 and 132a, the lower winding of relay CU5P, back contact 80 of relay AJPS and terminal C. Then, with the acknowledging switch restored to its normal position, all of the acknowledging relays except relay CU5P are released and magnet valve MV becomes energized over a circuit path connected in multiple with indication unit CU5 and including front contacts 132 and 133 of acknowledging relay CU5P, contact 108—107 of switch AS, and back contacts 97, 98, 99, 100 and 101 of acknowledging relays CU6P, CU1P, CU2P, CU3P and CU4P, respectively, as will be understood from an inspection of Fig. 5.

If, the train-carried cab signal equipment is responding to 75 code, as would result when the train traverses section O—P lying immediately to the rear of occupied section P—Q, then code detecting relay H alone is energized, and unit CU5 of cab signal CS becomes illuminated over a circuit which may be traced from terminal B through front contact 87 of relay H, back contact 116 of relay AJPS, back contact 122 of relay AJP1, back contact 128 of relay BJPS, back contact 134 of relay BJP1, the filament of indication unit CU6, back contact 135 of relay BJP1, back contact 131 of relay BJPS, back contact 125 of relay AJP1, back contact 119 of relay AJPS and front contact 92 of relay H to terminal C. The illumination of unit CU6 indicates that the section next in advance of the section being traversed is occupied.

With relay H only energized, the previously mentioned stick circuit of relay CU5P and the energizing of magnet valve MV are opened due to the releasing of relay BJP1. By operating acknowledging switch AS, all of the acknowledging relays become sequentially energized over their previously mentioned pick-up circuits, and when relay CU5P picks up it completes for itself a stick circuit which corresponds to the above-traced circuit of indication unit CU6 up to that unit but then leaves that circuit to pass through its own front contacts 136 and 136a, the lower winding of relay CU5P and back contact 80 of relay AJPS or back contact 112 of relay BJPS to terminal C. The acknowledging switch AS may now be restored to its normal position, whereupon all acknowledging relays except relay CU5P are released, and magnet valve MV becomes energized over a circuit path connected in multiple with unit CU6 and which circuit path includes front contacts 136 and 137 of relay CU6P, contact 108—107 of switch AS, and back contacts 98, 99, 100, 101 and 102 of relays CU1P, CU2P, CU3P, CU4P and CU5P, respectively, as is readily apparent from an inspection of Fig. 5.

When the cab signal equipped train is following another train in a block, no energy then is supplied from the rails to relay MR and all decoding relays are released to control indication unit CU7 of cab signal CS to its lighted condition, the unit being energized over a circuit passing from terminal B through back contact 140 of relay H, the filament of unit CU7 and back contact 141 of relay H to terminal C.

The entrance of the cab signal equipped train

on an occupied section and the consequent release of relay H opens the previously mentioned stick circuit of acknowledging relay CU6P and also the previously traced energizing circuit of magnet valve MV so that indicator AK is caused to sound. Acknowledging switch AS may be operated to complete the previously traced pick-up circuits of the acknowledging relays and all acknowledging relays then pick up. Relay CU7P when picked up completes for itself a stick circuit path connected in multiple with indication unit CUT and including its own front contact 142a, its lower winding, back contact 80 of relay AJPS or back contact 112 of relay BJPS, and terminal C. The switch AS may now be restored to its normal position whereupon all acknowledging relays except relay CU7P are released, and an energizing circuit for magnet valve MV is established to terminate operation of indicator AK. This energizing circuit of magnet valve MV extends from terminal B through back contact 140 of relay H, front contact 142 of relay CU7P, contact 108-107 of switch AS, the winding of magnet valve MV, back contacts 99, 100, 101, 102 and 103 of relays CU2P to CU6P, respectively, front contact 143, and back contact 141 of relay H to terminal C.

It is readily apparent from the foregoing description of the apparatus of Fig. 5 that I have provided novel and improved cab signaling apparatus wherewith an increased number of indications may be controlled by the customary few individual code rates by providing apparatus responsive to each individual rate of coding and to combined codes formed by a selected two of such rates repeated alternately.

It should be noted that the cab signaling apparatus represented in Fig. 5 employs six acknowledging relays one for each of the restrictive indications displayed by signal CS. These relays are so controlled by the decoding relays and by acknowledging switch AS that the relays are picked up in sequence when the acknowledging switch AS is reversed, and when once picked up, the relay associated with the particular signal indication unit controlled by the decoding relay completes for itself a stick circuit which is connected in multiple with its associated signal unit. Then, when the acknowledging switch is restored to its normal position, all of the acknowledging relays become released except the relay with the prepared stick circuit, and an energizing circuit for the magnet valve MV of audible indicator AK is established, this circuit being carried through front contacts of the energized acknowledging relay and back contacts of the remaining or deenergized acknowledging relays.

The cab signaling apparatus illustrated in Fig. 5 and hereinbefore described may be modified to provide a novel and improved signaling system incorporating means wherewith the number of sections or blocks in which restrictive indications are displayed may be varied in accordance with certain distinctive classifications of trains. Such trains may be classified in any suitable manner, but for the sake of illustration I shall assume that such trains are classified in accordance with the distance required for a full service application of the brakes to bring a train of each of such classes of trains to a stop from its authorized maximum speed.

In connection with such train classifications, it should be pointed out that, other factors re-

maining constant, the braking distance required for a full service application of the brakes to stop a train varies in accordance with the overall braking factor of such train, that is, the ratio of the available braking force to the weight of the train. Generally speaking, passenger trains are equipped with braking apparatus providing a much higher braking ratio than freight trains, and freight trains often are divided also into high and low speed trains according as such trains possess relatively high or relatively low braking ratios. I have illustrated in Fig. 6 a representative authorized maximum speed for each of three distinctive classes of trains, and have represented also a typical braking-distance curve for each of the represented classes of trains, the curves representing the manner in which a full service application of the brakes effects the stopping of trains of each of the represented classes from such authorized maximum speeds.

Referring to Fig. 6, a low speed freight train having an assumed braking ratio of 15% and an authorized maximum speed of 70 miles per hour is represented in curve a; a high speed freight train having an assumed braking ratio of 30% and an authorized maximum speed of 80 miles per hour is represented in curve b; and a passenger train having an assumed braking ratio of 80% and an authorized maximum speed of 100 miles per hour is represented in curve c. As is readily apparent from an inspection of Fig. 6, the braking distance required for a full service application of the brakes to bring trains of each of the several classes there represented to a stop varies widely. For example, a train of class a requires a braking distance of approximately 24,500 feet (18,000 feet plus 35% safety factor) to bring that train to a stop from its authorized maximum speed of 70 miles per hour; a train of class b requires approximately 19,500 feet (13,000 feet plus 50% safety factor) to bring such train to a stop from its 80 miles per hour authorized maximum speed; whereas a train of class c requires but 14,000 feet (9,000 feet plus 56% safety factor) to bring such train to a stop from its 100 miles per hour authorized maximum speed. Also, the distances required to bring a train of each of the classes illustrated from a medium speed, such for example as the represented medium speed of 35 miles per hour, to a stop are indicated in Fig. 6 on the extreme right-hand end of the broken line braking-distance curves of Fig. 6. From an inspection of these broken line curves shown in Fig. 6 it can be seen that for trains of classes a, b and c, the distances required to stop such trains from their medium speeds are of the order of 4,700 feet, 3,000 feet and 1,800 feet, respectively.

In view of the foregoing discussion, it is readily apparent that when trains of each of the represented classes are operated over the same stretch of railway track and are signaled alike, in order to insure that all trains will be able to come to a stop short of an occupied block, it is necessary that all of the trains be provided with a restrictive indication at a point approximately 25,000 feet to the rear of such occupied block, this distance obviously being determined by the distance required by trains of the class (a) which requires the maximum distance in which to stop.

Thus, assuming that the stretch is divided into consecutive sections or blocks of the customary length of 5,000 feet each, in order to receive an

unrestricted indication under the above conditions, five clear blocks must intervene between each train and the next block occupied in advance although such spacing is in reality required for only class *a* trains due to their relatively long braking distances. It is apparent, therefore, that if the above-mentioned conditions obtain, the movements of trains on the stretch may be materially curtailed since both the high speed freight (class *b*) and the passenger (class *c*) trains are prematurely given restrictive indications since such trains could operate at unrestricted speeds for considerable distances and still be brought to a stop short of the occupied block. For example, a class *b* train requires a restrictive indication only when it arrives at a point approximately 20,000 feet to the rear of an occupied block and hence could operate at unrestricted speeds when but four blocks intervene between it and the preceding train. Similarly, a passenger train could operate at full speed with but three blocks intervening between it and the train in advance since such train requires a restrictive indication to be given at a point only some 14,000 feet to the rear of the occupied block. It follows, therefore, that if the number of blocks in which the restrictive indications are displayed are varied in accordance with the class of train signaled, it then may be possible to decrease the distances required between successive trains and increase the capacity of the track.

In order, therefore, to obtain the advantages discussed above, I propose to signal trains of different classes in different manners, utilizing only cab signal equipment and dispensing with the use of wayside signals as distant signals, and while it is contemplated that locomotives regularly assigned to one class or another may be provided with apparatus arranged in a manner to be explained in detail presently for supplying only the correct signal indication for its assigned class, I also contemplate the provision of cab signaling equipment incorporating suitable selecting means wherewith a locomotive may be assigned to any one of the several classes and may, by proper operation of the selecting means, afford the correct signal indications for the class to which it is assigned.

In describing the apparatus referred to above, I shall assume that a train equipped with such apparatus operates over a stretch of track, such as is shown represented in Fig. 1, provided with trackway apparatus capable of supplying the trackway with a plurality of distinctive codes. This type of wayside apparatus may, for example, be of the type illustrated in Fig. 2 and capable of supplying the rails of each section with one or another of a plurality of distinctive codes each of which is constituted by coding the supply of trackway energy either individually at one or another of a plurality of distinctive code rates or alternately at first one and then another of two of such code rates. It is contemplated also that the wayside signals shown in Fig. 2 and selectively controlled by each distinctive code supplied to the rails of its section will take the form suitable for block signals, so controlled as to indicate only whether its associated section is or is not occupied. That is to say, the wayside signals employed no longer function as distant signals to indicate traffic conditions in advance of the sections associated with such signals, but might, for example, be two-position dwarf signals one positioned to mark the en-

trance of each section and controlled to a clear or to a restrictive indication according as its associated section is unoccupied or occupied. The manner in which the above-mentioned control of the block signals is established by decoding apparatus such as is shown in Fig. 2 will readily be apparent from an inspection of the apparatus there represented, it being noted that relay *H* only is required to detect the presence of a train in a section. Hence, the associated signal may be controlled to its clear indication when relay *H* of Fig. 2 is picked up to indicate the associated section is unoccupied, and the signal may be controlled to its restrictive indication when relay *H* is released to indicate that the section is occupied. The remainder of the decoding apparatus shown in Fig. 2 is employed, however, to control, in accordance with traffic conditions in a section and in advance of that section, the supply of trackway energy to the section next in the rear, in the manner and by circuits corresponding to those previously pointed out in detail in connection with the apparatus of Fig. 2.

In connection with a stretch of track provided with block signals and code transmitting apparatus of the type mentioned, I propose to employ cab signal apparatus capable of displaying a plurality of indications and having selecting means wherewith the character of the indications displayed in response to different codes may be varied in accordance with certain predetermined conditions of the selecting means. A preferred form of such cab signal apparatus is shown in Fig. 7 and which apparatus, as is readily apparent from an inspection of this figure, is substantially similar to the cab signal apparatus shown in Fig. 5 and described in detail in connection therewith, the apparatus illustrated in Fig. 7 being modified chiefly by substituting a four-indication cab signal *CSI* for the seven-indication cab signal *CS* of Fig. 5, and to agree with the reduced number of cab signal units, the number of acknowledging relays is reduced to three or one for each restrictive signal indication unit of signal *CSI*. An additional modification is the provision in the apparatus of Fig. 7 of suitable selecting means, here shown as a selector lever *LS* having three positions one for each of the different train classifications. The positions of the selector lever are designated by the reference characters *a*, *b* and *c* to correspond respectively to the three assumed classes *a*, *b* and *c* of trains. Controlled by selector *LS* are a plurality of contacts which are selectively interposed into or cut out of circuits controlled by the train-carried decoding relays, whereby the character of the indication displayed by signal *CSI* in response to different codes may be controlled in a manner to be made clear presently.

In describing the operation of the decoding apparatus shown in Fig. 7, which apparatus is similar to and responds to each distinctive code in a manner similar to that hereinbefore described in detail in connection with the decoding apparatus illustrated in Figs. 2 and 5, I shall refer to the table illustrated in Fig. 4 setting forth the various positions assumed by each decoding relay in response to the different codes received from the track rails, and shall also refer to Fig. 8 wherein is set forth in tabular form the various indications displayed by the cab signal *CSI* according to the position of lever *LS* and the code received from the rails.

In the following description, I have omitted

describing the manner in which the acknowledging relays incorporated into the apparatus of Fig. 7 are controlled since it is believed that the control of such relays will readily be apparent from an inspection of the drawing taken in connection with the foregoing description of the operation of the apparatus represented in Fig. 5. It should, however, be pointed out that the selector lever LS functions to select the proper acknowledging relay, i. e. the relay that corresponds with the signal aspect selected by lever LS to be controlled by the decoding relays shown in Fig. 7, and enables the proper acknowledging relay to complete for itself its stick circuit whereby such relay is held energized under the control of such decoding relays. The acknowledging relays shown in Fig. 7 function in the same manner as the similar relays shown in Fig. 5, to energize magnet valve MV of audible indicator AK over a circuit completed over front contacts of the energized acknowledging relay and back contacts of the remaining or de-energized acknowledging relays.

I shall first assume that a locomotive equipped with apparatus similar to that shown in Fig. 7 is following another train in a section so that no trackway energy is received from the rails of the section by master relay MR carried by the following train. Under such assumed conditions, master relay MR is inactive and all decoding relays carried by the following train are released (see columns *j* to *p*, inclusive, of Fig. 4). This is the condition in which the apparatus is illustrated in Fig. 7, and in this condition of the apparatus, lamp R of cab signal CS1 is caused to become illuminated over a simple circuit which may be traced from terminal B through back contact 140 of relay H, the filament of lamp R of signal CS1 and back contact 141 of relay H to terminal C. Regardless, therefore, of the position of selector lever LS, signal CS1 displays its most restrictive indication R whenever the equipped locomotive follows another train in an occupied block.

If, however, the train-carried master relay shown in Fig. 7 is responding to 75 code received from the rails of the section, as would result when a train is traversing a section immediately in the rear of an occupied block, and relay H accordingly is picked up, then signal CS1 is caused to display its "yellow" aspect Y by a circuit which extends from terminal B through front contact 87 of relay H, back contact 116 of relay AJPS, back contact 122 of relay AJP2, back contact 128 of relay BJPS, then through either of two alternate paths one of which includes contact 151-152 of lever LS (closed only in the *a* position of the lever) and the other path of which includes contact 151-153 or 151-154 of lever LS (closed respectively in the *b* and *c* positions of the lever) and back contact 134 of relay BJPI, then through the filament of lamp Y of signal CS1 to two alternate paths one of which comprises *a* position lever contact 156-159 and the other path of which comprises back contact 135 of relay BJPI and *b* position lever contact 157-159 or *c* position lever contact 158-159, then through back contact 131 of relay BJPS, back contact 125 of relay AJP1, back contact 119 of relay AJPS and front contact 92 of relay H to terminal C. It is readily apparent, therefore, that regardless of the position of lever LS, lamp Y of signal CS1 is illuminated and displays its aspect whenever master relay MR

of Fig. 7 responds to 75 code, as is indicated in columns 2, 3 and 4 of Fig. 8. This indication is common to each class of trains since all trains traversing the block supplied with 75 code, that is, the block next in the rear of an occupied block, should be prepared to stop short of the entrance to the occupied block.

In the event that relay MR of Fig. 7 is responding to 120 code as would result when the train occupies the second section to the rear of an occupied section, decoding relays H, BJ and BJPI are picked up and the other decoding relays are released, and signal CS1 displays its "yellow" indication Y when lever LS is in its *a* position, and with the lever in its *b* or *c* position, the signal then displays its "yellow" over "green" Y/G indication. Under the above conditions, lamp Y of signal CS1 is illuminated when lever LS is in its *a* position by a circuit which corresponds to the circuit previously traced for lamp Y when the selector lever is in its *a* position and 75 code is received from the trackway. If however, lever LS is in its *b* or *c* position, then indication unit Y/G becomes illuminated over a circuit which extends from terminal B through front contact 87 of relay H, back contact 116 of relay AJPS, back contact 122 of relay AJP1, back contact 128 of relay BJPS, lever contact 151-153 or 151-154, front contact 129 of relay BJPI, the filaments of indication unit Y/G of signal CS1, front contact 130 of relay BJPI, lever contact 157-159 or 158-159, back contact 131 of relay BJPS, back contact 125 of relay AJP1, back contact 119 of relay AJPS, and front contact 92 of relay H to terminal C. It can be seen, therefore, that the decoding apparatus of Fig. 7 responds to 120 code to cause signal CS1 to display its "yellow" or its "yellow" over "green" aspect according as selector lever LS is in its *a* or in its *b* or *c* position. Thus, a train operating in the second block in the rear of an occupied block is signaled to proceed under one or another of two distinctive signal aspects selected in accordance with the distance required to bring such train to a stop. Trains of class *a* requiring the maximum distance in which to stop are given a more restrictive aspect than are trains of the other classes capable of stopping more quickly. This permits trains of such other classes to proceed at the maximum speed permissible under the given traffic conditions and braking distances, and allows such trains to follow preceding trains at a higher rate of speed, based upon their superior braking power.

If, now, the following train is traversing the third section in the rear of an occupied section, then 120-75 code is supplied to master relay MR of Fig. 7 and relays H, BJ, BJPI, BJP2 and BJPS are energized and relays AJPS, AJP2, AJP1 and AJ are deenergized. Signal CS1 now is caused to display its "yellow" over "green" aspect, over a circuit which may be traced from terminal B through front contact 87 of relay H, back contact 116 of relay AJPS, back contact 122 of relay AJP1, front contact 123 of relay BJPS, the filaments of indication unit Y/G of signal CS1, front contact 124 of relay BJPS, back contact 125 of relay AJP1, back contact 119 of relay AJPS, and front contact 92 of relay H to terminal C. The "yellow" over "green" aspect is displayed to all trains traversing the section third in the rear of the occupied section since such signal aspect requires a train to approach the next signal at not exceeding medium speed and trains of each of the three classes here assumed have sufficient

distances (over 10,000 feet) between them and the occupied section to break when moving at the medium speed for their respective class (see braking distance curves of Fig. 6).

When the following train is traversing the fourth section in the rear of an occupied block and its train-carried master relay MR is responding to 180 code, then only decoding relays H, AJ and AJP1 are energized and signal CS1 displays its "yellow" over "green" aspect if selector lever LS is in either its *a* or *b* position, and its "green" aspect if the selector is in its *c* position. With lever LS in either its *a* or *b* position, signal CS1 is caused to display its "yellow" over "green" aspect over a circuit which extends from terminal B through front contact 87 of relay H, back contact 116 of relay AJPS, front contact 117 of relay AJP1, lever contact 172-173 or 172-174, the filaments of indication unit Y/G of signal CS1, lever contact 175-177 or 178-179, front contact 118 of relay AJP1, back contact 119 of relay AJPS and front contact 92 of relay H to terminal C. However, with lever LS in its *c* position, signal CS1 then is caused to display its "green" aspect over a circuit which corresponds to the above traced circuit up to lever contact 172-173 and then passes from that contact through lamp G of indicator CS1 to lever contact 179-177, the remainder of this circuit corresponding to the above-mentioned circuit for indication unit Y/G of signal CS1. The "approach medium" or Y/G aspect is displayed to trains of classes *a* and *b* traversing the fourth section to the rear of an occupied section since trains of either of such classes are operating within the distance of the occupied section required by the associated braking curves to be traversed at a restrictive speed (see braking curves *a* and *b*, Fig. 6). However, a train classified in class *c* is to the rear of the occupied section a distance in excess of that required to bring such train to stop from its authorized maximum speed, and hence such train is permitted to operate at an unrestricted speed in the fourth block in the rear of an occupied block.

Assuming now that a following train is traversing the fifth block in the rear of an occupied section so that as a result its master relay MR shown in Fig. 7 is following 183-175 code, then the decoding relays H, AJ, AJP1, AJP2 and AJPS carried thereby will be energized. If, under the conditions assumed, lever LS is in its *a* position, then signal CS1 is illuminated and is caused to display its "yellow" over "green" aspect over a circuit which extends from terminal B through front contact 87 of relay H, front contact 88 of relay AJPS, back contact 105 of relay BJPS, contact 182-183 of lever LS, the filaments of indication unit Y/G of signal CS1, lever contact 186-189 of lever LS, back contact 196 of relay BJPS, front contact 91 of relay AJPS and front contact 92 of relay H to terminal C. If, under the conditions assumed, lever LS is in its *b* or in its *c* position, then signal CS1 is caused to display its "green" aspect by a circuit which corresponds to the above traced circuit for the energization of the "yellow" over "green" aspect of signal CS1 up to the lever contact 182, then passing through lever contact 182-184 or 182-185, the filament of lamp G of signal CS1, lever contact 187-189 or 188-189, and the circuit corresponding to the above traced circuit for unit Y/G of signal CS1.

The different classes of trains in the fifth section are provided with different indications since

as can be seen from an inspection of the braking distance curves of Fig. 6, trains of classes *b* and *c* are positioned beyond the point at which they must start braking in order to stop short of an occupied section, whereas trains of class *a* still are within the distance from the occupied section that requires such trains to operate at restrictive speeds in order to insure proper stopping.

10 All trains regardless of class are provided with a "green" aspect when traversing sections at least six blocks in the rear of an occupied block, since such sections are positioned beyond the point at which a brake application is required to bring the train most difficult to stop, to a stop short of an occupied block. The track rails of the section six blocks removed from an occupied section are supplied with 180-120 code and as a result all decoding relays carried by the following train are energized so that signal CS1 is caused to display its "green" aspect over a circuit which may be traced from terminal B through front contact 87 of relay H, front contact 88 of relay AJPS, front contact 89 of relay BJPS, the filament of lamp G of signal CS1, front contact 90 of relay BJPS, front contact 91 of relay AJPS and front contact 92 of relay H to terminal C. It should be noted that since 180-120 code represents the most unrestricted traffic condition in the stretch and is supplied to all sections lying in the rear of the fifth section from an occupied block, then any train traversing a section supplied with 180-120 code will receive an unrestricted "green" indication regardless of the position of selector lever LS.

From the foregoing description of the operation of the apparatus of Fig. 7, it is readily apparent that I have provided a novel and improved signaling system so arranged as to permit the maximum permissible speed under each condition of traffic in advance of each train, and which regulates the spacing between successive trains in accordance with the braking characteristics of the particular following train. It follows that since the spacing of trains on a stretch is determined by apparatus embodying my invention in accordance with the braking characteristics of each distinct class of trains and no longer is determined by the distance required by trains most difficult to stop, the capacity of a stretch of track may be materially increased and the movement of traffic over such stretch may be facilitated.

It further is apparent from the foregoing description that apparatus embodying my invention provides means whereby not only the spacing between successive trains may be regulated in accordance with the braking ratio of the following trains, but also incorporates means wherewith a locomotive, when assigned to any one of the several different classes of trains, may afford the proper signal indication to enforce the predetermined spacing between a train of its assigned class and the preceding train.

65 It should, of course, be understood that if a locomotive is to be assigned regularly to a particular class of service, the train-carried apparatus of that locomotive then may be arranged in such manner as to provide only the signal indications required to enforce proper spacing of trains of that class. For example, the locomotive might be provided with apparatus similar to that shown in Fig. 7 but having a selector lever locked in the position corresponding to the assigned class, or, if desired, the decoding apparatus car-

ried by the train might be provided with only such circuits which provide the correct indications to enforce proper spacing for the particular class of trains to which this locomotive is assigned.

An advantage of apparatus of the type illustrated in Fig. 7 is the provision of a signaling system of the type which I shall term a six-block, four-indication system, wherein four indications are employed to control the movements of trains in accordance with both traffic conditions six blocks in advance of the train and the braking distance required to bring such train to a stop short of an occupied block.

It is to be understood, of course, that while apparatus embodying my invention and hereinbefore described illustrates means for utilizing only six different codes constituted by using one or another of three different code rates individually or any two of such three rates alternately, such apparatus can readily be modified to utilize any desired number of rates of coding employed either individually or in different combinations constituted by using such plurality of rates two at a time. For example, the wayside apparatus shown in Fig. 2 might readily be modified to furnish and to be selectively responsive to each of four distinct individual code rates and to each distinctive code combination formed by coding energy alternately at first one and then another of two of such four individual rates. To provide such modification would require merely the provision on transmitter CT of Fig. 2 of another coding contact periodically operated at a distinct code rate, thereby providing an additional or fourth individual code. Then, by employing a relay similar to the AJ and BJ relays but responsive only to the additional individual code rate, and by providing this additional code selecting relay with three repeater relays to correspond with the three repeater relays of relays AJ and BJ, there would be provided a modified system responsive to the four individual codes and to the combinations of such four codes two at a time. Since the number of blocks governed usually is limited by the number of distinctively different codes available, the use of four distinctive individual rates plus the use of six combined rates (the combination of four codes taken two at a time or six combined codes in all) then would provide a ten block, eleven-indication wayside signal system capable of indicating traffic conditions for ten blocks in advance of each section. Similarly, the cab signal apparatus shown in Fig. 5 might readily be modified to provide a ten block, eleven-indication cab signal system, and the apparatus shown in Fig. 7 modified to permit a relatively large number of distinct classifications of trains.

In addition, my invention also contemplates the provision of railway traffic controlling apparatus selectively responsive to each of the many possible combinations of individual and combined codes. For example, a single combined code might be used in combination with three individual rates to provide a four block, five-indication system. The wayside apparatus of a typical one of the sections of such system is illustrated in Fig. 9, wherewith it is contemplated that the 75, the 120, the 120-75 and the 180 codes will be employed.

Referring now to Fig. 9, it is readily apparent that such apparatus is substantially similar to the wayside apparatus shown in Fig. 2 except that a two-unit wayside signal S replaces the

three-unit signal shown in Fig. 2, and the three repeater relays associated with the 180 code selecting relay AJ no longer are required. The apparatus illustrated in Fig. 9 operates to selectively control both the supply of trackway current to the section next in the rear and the associated wayside signal in response to operation of relay TR by trackway energy of the three individual and the one combined code formed by cyclically coding energy alternately at one or another of two of such individual rates. That is to say, when relay TR responds to 180 code, relays H and AJ are picked up as shown in Fig. 9, and 180 code current is supplied to the rails of the section next in the rear over a circuit extending from terminal BX through contact 180-180a of coder CT, front contact 145 of relay AJ, front contact 59 of relay H and the primary winding of track transformer TT to terminal CX. When, however, relay TR is shunted by a train in the associated section, both relays H and AJ release and 75 code current is supplied to the rails of the next section over a circuit passing from terminal BX through contact 75-75a of coder CT, back contact 43 of relay H and the primary winding of transformer TT to terminal CX. After the train vacates the section shown in Fig. 9, relay TR is caused to operate at the 75 code rate and relay H picks up to condition the apparatus to supply 120 code current to transformer TT over a circuit extending from terminal BX through contact 120-120a of coder CT, back contact 55 of relay BJPI, back contact 56 of relay BJPS, back contact 146 of relay AJ, front contact 59 of relay H and the primary winding of transformer TT to terminal C. When the train vacates the section next in advance of the section shown in Fig. 9, relay TR is caused to operate at the 120 code rate and relays H and BJ are picked up. Relay BJPI also picks up, and a combined 120-75 code is supplied to the rails of the section in the rear, this code being supplied over a circuit having two branch paths, one extending from terminal BX through contact 120-120a and contact point 15a to contact finger 15 of coder CT, the other path extending from terminal BX through contact 75-75a and contact point 15c to contact finger 15 of coder CT, and the circuit then extends from contact finger 15 of coder CT through front contact 64 of relay BJPI, back contact 56 of relay BJPS, back contact 146 of relay AJ, front contact 59 of relay H, and the primary winding of transformer TT to terminal CX. It follows that with coder CT alternately closing contacts 15-15a and 15-15c for two second intervals, there is supplied to the section in the rear, current coded at the 120-75 combined code rate. When relay TR responds to this combined 120-75 code, relays H, BJ, BJPI, BJP2 and BJPS are picked up, and 180 code current is supplied to the section in the rear over a circuit which may be traced from terminal BX through contact 180-180a of coder CT, front contact 65 of relay BJPS, back contact 146 of relay AJ, front contact 59 of relay H and the primary winding of transformer TT to terminal CX. It is believed that the manner in which the decoding relays H, AJ, BJ, BJPI, BJP2 and BJPS cooperate to selectively control the signal represented in Fig. 9 will readily be apparent from an inspection of the drawings taken in connection with the description of the apparatus illustrated in Fig. 2, and further detailed explanation is deemed unnecessary except to point out that when only four different codes are utilized, the number of

distinctive indications controlled thereby is reduced to five in number.

It is to be noted that the coders CT are represented diagrammatically in the drawings, as incorporating certain coding contacts which have no apparent function in this case, that is, the description contains no illustrated or described function for such contacts. The coders have been illustrated in this manner, however, since it is customary to construct code transmitters having a standard number of contacts, hence each coder CT is represented diagrammatically as a coder of standard construction. Also, it is to be noted (see Fig. 1) that traffic on the stretch of track X is signaled only for eastbound traffic, hence to permit moves in either direction, another track or other tracks would be provided so that the track X may comprise only one track of a multiple-track railway. The coding contacts which are shown idle or unused are thus available for use in coding the current supplied to the rails of the other tracks of the road.

Another particularly useful modification of the apparatus embodying my invention is shown in Figs. 10a and 10b. In these figures, the customary wayside apparatus selectively responsive to energy coded at the 75 and 180 code rates and utilized to control a two block, three-indication signal SD, is shown modified in accordance with my invention to control an additional signal ACS in response to a combination code formed by cyclically coding the supply of trackway energy alternately at first one and then the other of two different rates of coding. In the particular embodiment of the apparatus illustrated in Figs. 10a and 10b and hereinafter described, it is contemplated that the additional signal ACS may be utilized to indicate the presence of fixed track hazards, such as curves, cuts, fills, tunnels, bridges or the like which require a modification of maximum speed for traffic operating thereover.

Referring now to Figs. 10a and 10b, a section of track D—E is illustrated as being defined at each end by means of the usual insulated track joints 2 and as having intermediate its ends a fixed hazard Z at which a speed not greater than a predetermined maximum speed is required for safety. The track section is provided with a code transmitter CT positioned adjacent its exit end E and with a code following track relay TR connected across the track rails at its entrance end D. A code selecting relay AJ is controlled by relay TR through the medium of its associated decoding unit DU—180; two "lock-out" relays FSA and BSA are controlled by relay TR in a manner to be explained in detail hereinafter; and a code detecting relay H is also controlled by relay TR over the usual circuit arrangements wherein relay H is picked up over a pick-up circuit which may be traced from terminal B through front contact 22 of relay TR, back contact 194b of relay H, front contact 195 of relay BSA, and the winding of relay H to terminal C. Relay H when picked up over the circuit just traced completes for itself a stick circuit which extends from terminal B through front contact 194 of relay H, front contact 195 of relay BSA and the winding of relay H to terminal C.

Relay AJ as shown is provided with two slow releasing repeater relays AJP1 and AJP2 each characterized by the provision of a slow release period slightly in excess of two seconds in duration and each controlled by relay AJ in a manner and by circuits which correspond to similar cir-

cuits shown in Fig. 2 and there described in detail.

It is contemplated that the stretch of trackway illustrated in Figs. 10a and 10b may be a portion of a stretch of electrified trackway in which the track rails 1 and 1a form a portion of the return path for the propulsion current, hence impedance bonds, designated by the reference characters 3, are shown located at each pair of insulated joints 2 to permit transfer of propulsion current around such joints but preventing similar transfer of the trackway signaling current. Two "lock-out" relays FSA and BSA are provided and are controlled respectively over front contacts and back contacts of relay TR, hence relay FSA functions as a front contact repeater relay and relay BSA functions as a back contact repeater relay of relay TR. The circuit of relay BSA also includes a front contact of relay FSA, and the relays FSA and BSA control in the usual and well-known manner the supply of trackway current to the section next in the rear, whereby the rails of the rear section are supplied with coded trackway energy under normal conditions but are supplied with steady or non-coded energy in the event that trackway energy leaks forwardly from the rear section into section D—E to falsely energize relay TR. In this manner, broken-down insulated rail joint protection is obtained for detecting and protecting against false operation due to a failure of a rail joint to insulate the trackway energy of the rear section from the advance section.

Section D—E also is divided at cut-section location Da into two subsections by means of insulated joints 2 interposed in the rails at that point. A code following relay TR1 is connected across the rails of advance subsection Da—E, adjacent cut-section location Da, and this relay controls an auxiliary relay BSA1 over an obvious circuit including back contact 200 of relay TR1. Relays TR1 and BSA1 function to cascade coded energy from the advance subsection Da—E to the rear subsection D—Da, as is readily apparent from an inspection of the drawings, but prevent the cascading of steady energy from the advance subsection to the adjacent rear subsection. This protection is afforded by virtue of the releasing of relay BSA1 when relay TR1 is held steadily energized on non-coded energy.

As can be seen from an inspection of Figs. 10a and 10b, the location of the fixed hazard in the trackway is such that it is not necessary to maintain a restrictive speed throughout the entire length of section D—E. In consequence, across the rails of the section adjacent the point at which unrestricted speed is permitted, is connected a code following relay XTR provided with an auxiliary relay XTF which it controls through the medium of a transformer XT. Auxiliary relay XTF controls an approach control relay 2AR over an obvious circuit including back contacts 163 and 161 of relay XTF; and relay 2AR in turn controls the supply to the rails of section D—E of the "clear" or 180 code and the fixed hazard indication or combination code formed alternately of repeated intervals of the 180 or "clear" code and another code rate, such as the 120 code rate previously mentioned in connection with the apparatus of Figs. 2, 5, 7 and 9.

In describing the operation of the apparatus shown in Figs. 10a and 10b, it first should be pointed out that a fixed hazard indication is displayed at signal location D only in the event that an otherwise unrestricted speed would be per-

missible in section D—E. That is to say, the fixed hazard indication code is supplied only when the section next in advance of section D—E is unoccupied so that but for the presence of the fixed hazard in section D—E, an unrestricted speed would be indicated at signal location D and 180 code would be supplied to the section. However, with a fixed track hazard in the section, the rails thereof normally are supplied with a combined code formed of repeated alternate intervals of the 180 code and another code, over a circuit having two alternate paths one of which passes from terminal BX through contact 180—180a of code transmitter CT and contact 15a—15 of transmitter CT and the other of which passes from terminal BX through contact 120—120a of transmitter CT and contact 15b—15 of transmitter CT, then through back contact 203 of relay 2AR and front contacts 162, 163 and 164 of relays 2H, 2BSA and 2FSA, respectively, provided for the section next in advance, and the primary winding of track transformer TT1 to terminal C.

With the rails of subsection Da—E supplied with combined 180—120 code, relays TR1 and BSA1 at location Da function to cascade such energy into the rear subsection D—Da and relay TR responds to such energy to cause relay AJ to be alternately picked up and released for two-second intervals. The alternate picking up and releasing of relay AJ causes relays AJP1 and AJP2 to be picked up also, and as a result auxiliary signal ACS is energized over an obvious circuit including front contacts 165 and 166 of relays AJP1 and AJP2, respectively. Also, since relay H is held energized in response to relay TR following code, signal SD is caused to display its clear indication by a simple circuit including front contacts 44, 66 and 167 of relays H, AJP1 and AJP2, respectively.

In the event that a train enters section D—E under the above conditions, the combined 180—120 code present in the rails of the section will be supplied to the train to control suitable train-carried apparatus later to be referred to, until such time as the train passes track hazard location Z at which is positioned relay XTR. When the train is moving between location Z and the exit end of the section, relay XTR is shunted and its code following contacts assume their released positions so that auxiliary relay XTF also releases. The releasing of auxiliary relay XTF completes the previously mentioned circuit for approach control relay 2AR, whereupon the latter relay picks up to close its front contact 204 and thereby establish an obvious circuit whereby the rails of section D—E are supplied with "clear" or 180 code over contact 180—180a of code transmitter CT. This 180 code supplied to the rails of section D—E after the train passes the hazard operates to control the train-carried apparatus later to be referred to, to an indication that permits an increased speed.

The operation of the apparatus illustrated in Figs. 10a and 10b when 75 code is supplied to the rails of section D—E will readily become apparent from an inspection of the drawing and further detailed explanation is believed to be unnecessary.

Fig. 11 illustrates a modified arrangement of a portion of the apparatus shown in Fig. 10b, in which modified arrangement the cut section location Da is positioned at the point at which resumption of maximum speed is permitted.

When cut section facilities are utilized at this point, the usual two lock-out relays BSA and FSA may be utilized to provide not only protection against cascading steady non-coded energy from one subsection to the next, but also to control over back contacts 170 and 171 of relay BSA the approach control relay 2AR shown in Fig. 10b, thereby selecting between supplying 180 or combined 180—120 code in accordance with traffic conditions in subsection Da—E.

Another modified arrangement of a portion of the apparatus shown in Fig. 10b is illustrated in Fig. 12. In connection with the apparatus of Fig. 10b, the modified arrangement shown in Fig. 12 may be employed to replace the cut section facilities at location Da and the "cut-out" track relay XTR located at fixed hazard location Z, and if this is done, it then is contemplated that the rails of section D—E will be supplied at its exit end with 180 code, which is received by the code following track relay XTR of Fig. 12 and is utilized to control code selecting relay AJ through the medium of decoding unit DU—180. The code selecting relay AJ as shown functions to establish circuits whereby the rear subsection D—Da is supplied with 180—120 code. That is to say, when 180 code is received by relay XTR so that relay AJ is picked up, the rails of the rear subsection are supplied with combined 180—120 code over a circuit passing from terminal BX through contact 180—180a and contact 15a—15 or from terminal BX through contact 120—120a and contact 15b—15 of coder CT, then through front contact 181 of relay AJ and the primary winding of the track transformer of the rear subsection to terminal CX. However, when 75 code is received by relay XTR, then relay AJ is released and completes at its back contact 190 a circuit over which 75 code is supplied to the rear subsection due to relay XTR opening and closing its front contact 191 at a rate corresponding to the code rate of the received trackway energy. In this manner each portion of the section is provided with a particular code of trackway energy representing the indication that is correct to be displayed in such portions respectively.

Fig. 13 illustrates subsection Da—E having a fixed hazard located adjacent its exit end E. Normally, combined 180—120 code is supplied to the rails of section D—E adjacent its exit end, and is received by a track relay XTR positioned at cut-section location Da located in the rear of the hazard and defining the beginning of the restrictive speed zone for the hazard. Relay XTR has associated therewith an AJ relay and two associated slow releasing relays AJP1 and AJP2, which relays cooperate in controlling circuits whereby a code transmitter CT1 at location Da supplies energy to the rails of the rear subsection. As is readily apparent from an inspection of the drawing, code transmitter CT1 functions to supply only 180 code to the rear subsection when relay AJP2 is picked up in response to relay XTR following combined 180—120 code received from the advance subsection; the 180 code being supplied over a circuit extending from terminal BX through contact 180—180a of coder CT1, front contact 192 of relay AJP2, and the primary winding of the track transformer of the rear subsection to terminal CX. Whenever relay AJP2 is released in response to relay XTR following 75 code, this 75 code is cascaded into the rear subsection over a circuit including

front contact 191 of relay XTR and back contact 193 of relay AJP2.

The apparatus illustrated in Fig. 14 illustrates a section of track normally supplied with "clear" or 180 code trackway energy, but provided with means responsive to the presence of a train upon a restrictive speed zone adjacent a hazard for supplying the 180-120 code to the section. The apparatus of Fig. 14 is characterized by the provision of two approach control relays 2AR and XAR, respectively. Relay 2AR is utilized to control the supply of trackway energy to section D-E and the other relay XAR is utilized to control relay 2AR. The relay 2AR is controlled by track relay XTR which is positioned at the point beyond which a restricted speed no longer is required.

In the normal condition of the apparatus of Fig. 14, a code detecting relay H controlled by suitable apparatus, such as is shown in Fig. 10a located adjacent signal location D, is energized to complete an obvious circuit including front contacts 205 and 206 of relay H for approach control relay XAR. With relay XAR energized, relay 2AR also is energized over a circuit extending from terminal B through front contact 207 of relay XAR, front contact 160f of relay XTF, the winding of relay 2AR, front contact 161f and front contact 208 of relay XAR to terminal C. Relay 2AR, energized, establishes a circuit whereby the rails of section D-E are supplied with 180 code trackway energy when clear traffic conditions in advance exist. This circuit may be traced from terminal BX through contact 180-180a of coder CT, front contact 204 of relay 2AR, front contacts 162, 163 and 164 of relays 2H, 2BSA and 2FSA, respectively, of the section next in advance, and the primary winding of transformer TT1 to terminal CX. When, however, section D-E is entered by a train so that relay H releases, relay XAR also releases to cause the release of approach control relay 2AR, whereupon 120-180 code is supplied to section D-E over a circuit which includes back contact 203 of relay 2AR and contact 15-15a of coder CT in series with contact 180-180a of coder CT or contact 15-15b of coder CT in series with contact 120-120a of coder CT.

As the train proceeds through section D-E and advances beyond the hazard, relay XTR is shunted so that auxiliary relay XTF releases to complete through back contacts 207b, 208b and 160, 161 of relays XAR and XTF, respectively, an alternate energizing circuit for relay 2AR, whereupon the latter relay picks up to close its front contact 204 and reestablish the previously traced circuit whereby section D-E is supplied with clear or 180 code.

The operation of the apparatus illustrated in Fig. 14 when 75 code is supplied to section D-E will readily become apparent from an inspection of the drawings, and further detailed explanation is believed to be unnecessary except to point out that approach control relay 2AR does not control the supply of 75 code to section D-E, hence this latter code may be supplied to the section regardless of the position of relay 2AR.

Another modification of the apparatus shown in Figs. 10a and 10b is illustrated in Fig. 15, wherein it is contemplated to approach control the form of trackway energy supplied to the rails of section D-E whereby train-carried apparatus on a train may be controlled to indicate that the train is approaching the end of an "approach" block, that is, that such train is ap-

proaching the limits of a block next in the rear of an occupied block. In Fig. 15, a code responsive relay XTR is connected across the rails of the section at the point at which it is desired that the "end-of-block" indication be displayed. Relay XTR controls a repeater relay XTF through the medium of transformer XT in such manner that relay XTF is held energized when relay XTR responds to coded energy received from the rails of the section, and relay XTF is released when a train is interposed between the exit end E of the section (at which trackway energy is supplied) and the location of relay XTR.

The rails of section D-E of Fig. 15 are supplied with "clear" or 180 code over an obvious circuit when the section in advance is unoccupied so that a relay H of such advance section is picked up. When the advance section is occupied and relay H of that section accordingly is released, "approach" or 75 code is supplied to the rails of section D-E normally over a circuit which extends from terminal BX through contact 75-75a of coder CT2, front contact 160f of relay XTR, back contact 199 of relay H associated with the section next in advance of section D-E, and the primary winding of transformer TT1 to terminal CX. If, however, with relay H of the section in advance released, a train in section D-E advances beyond the location of relay XTR and shunts that relay to cause the release of relay XTF, the just traced normal circuit of the "approach" code is opened and such code is supplied to the rails of section D-E over an alternate circuit which may be traced from terminal BX through contact 75-75a of coder CT2, contact 209-209a of coder CT2, back contact 160 of relay XTF, back contact 199 of relay H and the primary winding of transformer TT1 to terminal CX. The "approach" or 75 code supplied over the above-traced alternate circuit is modulated in a distinctive manner by the action of cam 14 of coder CT2, which cam as shown is provided with one tooth or projection which engages its associated contact member 209 to close contact 209-209a during two-fifths of the revolution of cam 14. When contact member 209 is not engaged by the projection of cam 14 (during the remaining three-fifths of each revolution of the cam), contact 209-209a is opened. It can be seen, therefore, that when relay XTF is released to interpose contact 209-209a of coder CT2 in the circuit over which "approach" or 75 code is supplied to section D-E, contact 209-209a functions to modulate such code by periodically interrupting and completing the circuit over which such code is supplied to section D-E, so that as a result the rails of section D-E are provided with short intervals of 75 code separated by somewhat longer intervals during which no code is supplied to the section. It is readily apparent that if the train in section D-E is provided with the customary train-carried code responsive apparatus for controlling a cab signal, such "modulated" 75 code will cause the train-carried apparatus alternately to energize the particular cab signal indications that correspond respectively with the 75 and the "no-energy" code conditions in the trackway, thereby causing the cab signal to display distinctive flashing indications to denote that the train is nearing the end of the "approach" block.

If desired, other forms of apparatus may be employed to cut out or to start the combined

or modulated codes which are supplied to the rails of section D—E by the apparatus illustrated in Figs. 10b, 13, 14 and 15. For example, Fig. 16 illustrates a track instrument TX of the well-known microphone type, operatively connected to the rail of section D—E at the point defining the limit of the restrictive speed zone and utilized to cut out the supply of the combined code and to start the supply of the normal code to the rails of section D—E. As shown, instrument TX controls the supply of energy to the primary winding of a transformer TTX, which transformer has its secondary winding connected through a full-wave rectifier to the winding of a relay XR. Normally, relay XR is released since the magnitude of current supplied through instrument TX to the primary winding of transformer TTX is constant. However, whenever a train in section D—E approaches instrument TX and causes it to vibrate, the magnitude of current supplied through the instrument is varied in response to the actuation of the contacting elements in the instrument, and an electromotive force is induced in the secondary winding of transformer TTX in response to the current variations in the transformer primary winding. This induced electromotive force is rectified into and is supplied to relay XR as unidirectional energy to pick up such relay, and when relay XR picks up, it is held up over an obvious stick circuit which extends from terminal B through back contact 234 of relay XAR, front contact 196 and the winding of relay XR to terminal C.

Normally, the apparatus shown in Fig. 16 is in the condition illustrated in the drawings, wherein approach control relay 2AR is energized over an obvious circuit including front contact 205 of relay H of section D—E and front contact 207 of relay XAR. In this condition of the apparatus, the rails of section D—E are supplied with 180 code under clear traffic conditions in advance, over an obvious circuit which includes contact 180—180a of coder CT and front contact 204 of relay 2AR.

Whenever a train enters section D—E to cause relay H to release, relays XAR and 2AR are also released and relay 2AR closes its back contact 203 to condition the apparatus of Fig. 16 to supply combined 180—120 code to the rails of section D—E over circuits similar to those pointed out in detail in connection with the apparatus illustrated in Fig. 14. This combined code is supplied to section D—E until such time as the actuation of instrument TX causes relay XR to pick up. When relay XR picks up, its previously traced stick circuit is completed at back contact 234 of relay XAR (which released in response to the release of relay H), and relay XR also completes an alternate energizing circuit for relay 2AR, which circuit may be traced from terminal B through front contact 197 of relay XR, back contact 207b of relay XAR and the winding of relay 2AR to terminal C. Relay 2AR accordingly picks up to close its front contact 204 and thus condition the apparatus to supply the rails of section D—E with 180 code.

When the train vacates section D—E, relay H of section D—E becomes reenergized and picks up to in turn cause relay XAR to pick up. The picking up of relay XAR opens the previously traced stick circuit of relay XR to release that relay, and also completes the previously mentioned circuit over which relay 2AR is held normally energized.

From the foregoing descriptions of the oper-

ation of the apparatus represented in Figs. 10a, 10b, 11, 12, 13, 14, 15 and 16, it is readily apparent that I have provided novel and improved means whereby the code supplied to the rails of a section may be changed or altered in accordance with traffic conditions in the section or in certain portions of the section. It is further apparent that I have provided means for supplying and for utilizing a combined code formed by coding energy alternately at first one and then another of two distinctive code rates, and which energy may be utilized to expand the number of controls effected by the trackway energy without increasing the number of individual rates of coding.

In connection with the various schemes just referred to for supplying the rails of a section with trackway energy which is coded at one or another of a plurality of different rates of coding or which is formed into a code combination of such rates according as a train occupies a restrictive speed zone or an unrestrictive speed zone in such section, I propose to provide novel and improved train-carried cab signal apparatus selectively responsive to each of the various codes of trackway energy supplied to the rails and received by the train. A preferred embodiment of such novel apparatus is illustrated in Fig. 17, wherein is shown the customary cab signal equipment of the type shown and described in United States Letters Patent No. 1,986,679 granted to L. V. Lewis on January 1, 1935, the apparatus shown in the patent for providing a distinctive indication for each of three individual code rates being modified in accordance with my invention to provide a distinctive indication whenever such apparatus responds to two of such code rates repeated alternately.

Referring now to Fig. 17, the train-carried apparatus there represented includes the usual receiving apparatus comprising the coils 85 and 86, amplifier AM and master relay MR, the decoding relays H, AJ and BJ, the cab signal CS1, the acknowledging indicator AK and switch AS, and the acknowledging relays YGP, YP, and RP. In addition to the above-mentioned customary apparatus, there are provided two slow releasing relays BJSR and AJSR each having a slow release period slightly longer than two seconds in duration, and indicator CS1 is provided with an extra distinctive indication unit XCS1. Also, the circuit for energizing relay BJ is carried over a back contact 24 of relay AJ, thereby insuring that relay BJ is released when the master relay is responding to 180 code and relay AJ is picked up.

I shall describe in detail only the operation of modified portions of the cab signaling system embodying my invention since the usual and well-known operation of such apparatus forms no part of my present invention. In the present modification, when the train-carried master relay MR is responding to 180 code, relays H and AJ are picked up. This is the condition in which the apparatus is illustrated in Fig. 17, and in this condition, lamp G of indicator CS1 is illuminated over a circuit which extends from terminal B through front contact 210 of relay AJ, back contact 211 of relay AJSR, back contact 212 of relay AJSR, the filament of lamp G of signal CS1, back contact 213 of relay AJSR, back contact 214 of relay AJSR, and front contact 215 of relay AJ to terminal C. It should be noted that acknowledging magnet valve MV is energized in multiple with lamp G of signal CS1

over the above traced circuit, the multiple path for magnet MV leaving the main circuit at the heel of back contact 212 of relay AJSR to extend through back contact 216 of relay YGP, back contact 217 of relay YP, contact 108—107 of acknowledging switch AS, the winding of magnet valve MV, back contact 218 of relay YP, and back contact 219 of relay YGP to rejoin the main circuit at the heel of back contact 213 of relay AJSR.

In the event the train enters that portion of a section supplied with combined 180—120 code, during the first two-second interval that 180 code is received from the rails, lamp G of signal CS1 is held illuminated. However, during the next two-second interval that 120 code is received, relay AJ releases to interrupt the previously traced energizing circuit for lamp G of signal CS1 and magnet valve MV, whereupon indicator AK is caused to sound. The release of relay AJ completes over its back contact 24 a circuit over which relay BJ is picked up in response to master relay MR following 120 code. With relay BJ picked up, acknowledging switch AS may be operated to its reverse position whereupon relay RP becomes energized over a circuit passing from terminal B through back contact 220 of relay AJ, contact 110—109 of acknowledging switch AS, the winding of relay RP and back contact 221 of relay AJ to terminal C, and relays YP and YGP also pick up in multiple with relay RP, the circuit of relay YGP including a front contact 235 of relay YP. The picking up of relay YGP completes a circuit whereby relay BJSR is energized, this circuit passing from terminal B through back contact 220 of relay AJ, front contact 222 of relay BJ, front contact 223 of relay YGP, back contact 224 of relay AJSR, the winding of relay BJSR, front contact 225 of relay BJ and back contact 221 of relay AJ to terminal C. Signal CS1 also is caused to display its Y/G indication, due to the energization of unit Y/G of signal CS1 over a circuit path connected in the above traced circuit for relay BJSR in shunt with relay BJSR, this path leaving the traced circuit at front contact 226 of relay BJSR and passing through back contact 227 of relay AJSR and the filaments of indication Y/G of signal CS1 to rejoin the circuit previously traced for relay BJSR, at a point intermediate the winding of relay BJSR and front contact 225 of relay BJ. Then, when the second interval of 180 code is received by the train-carried apparatus shown in Fig. 17, relay AJ picks up and relay BJ releases, thereby establishing an energizing circuit for relay AJSR, which circuit may be traced from terminal B through front contact 210 of relay AJ, front contact 228 of relay BJSR, the winding of relay AJSR and front contact 215 of relay AJ to terminal C. With both relays AJSR and BJSR picked up, the supplemental indication unit XCS1 becomes illuminated over a circuit passing from terminal B through front contact 229 of relay AJSR, front contact 230 of relay AJSR, the filament of signal unit XCS1, front contact 231 of relay AJSR and front contact 232 of relay AJSR to terminal C.

The acknowledging switch AS may now be restored to its normal position, thereby interrupting the previously mentioned energizing circuits for relays RP, YP and YGP, and establishing for magnet valve MV a circuit which extends from terminal B through front contact 229 of relay AJSR, back contact 216 of relay YGP,

5 back contact 217 of relay YP, contact 108—107 of acknowledging switch AS, the winding of magnet valve MV, back contact 218 of relay YP, back contact 219 of relay YGP, and front contact 232 of relay AJSR to terminal C. The energization of magnet valve MV silences indicator AK.

As long as the train traverses the zone of track supplied with combined 180—120 code, relays AJ and BJ are alternately energized and de-10 energized for two-second intervals to thereby alternately energize relays BJSR and AJSR for similar intervals. Relay AJSR is energized over its previously traced circuit during each two-second interval that relay AJ is picked up when relay MR responds to 180 code; and such relay is held in its picked-up position by virtue of its slow releasing characteristics during the alternate two-second intervals that relay AJ is released in response to relay MR following 120 code. 15 Relay AJSR accordingly is held continuously energized when relay MR responds to the combined 180—120 code, and as a result front contact 236 of relay AJSR is held closed to prepare a circuit for energizing relay BJSR. This circuit may be traced from terminal B through back contact 220 of relay AJ, front contacts 222 of relay BJ, front contact 236 of relay AJSR, the winding of relay BJSR, front contact 225 of relay BJ, and back contact 221 of relay AJ to terminal C. It can be seen that the above traced circuit for relay BJSR is completed and relay BJSR is energized during each two-second interval that relay BJ is picked up in response to relay MR following 120 code; and that by virtue of its slow releasing characteristics relay BJSR is held in its picked-up position during the alternate two-second intervals that relay BJ is released in response to relay MR following 180 code. The relays AJSR and BJSR accordingly are held continuously in their picked-up conditions in response to the combined 180—120 code received from the trackway and it follows that such relays control indication unit XCS1 continuously to display an illuminated aspect in response to such combined code.

45 Then, when the train vacates the zone supplied with the combined code and master relay MR responds again to unmodulated 180 code, relay AJ is held steadily picked up and relay BJ releases. 50 At the end of its two-second release interval, therefore, relay BJSR will release due to the interruption of its previously traced circuit, and with front contact 228 of relay BJSR opened, relay AJSR also will release. The apparatus accordingly is restored to the condition 55 first described wherein a circuit is established for lamp G of signal CS1.

From the foregoing description of the apparatus of Fig. 17, it is readily apparent that I have 60 provided novel and improved means wherewith cab signaling apparatus arranged to provide a plurality of distinctive indications one for each of a plurality of different code rates may be arranged to provide additional indications in response to code combinations formed by two of such different rates repeated alternately. It 65 further is apparent that means embodying my invention requires a minimum of apparatus to convert the customary cab equipment into one providing distinctive indications for combined codes. In addition, it can be seen that the cab signaling equipment embodying my invention can be utilized in its customary manner throughout the entire stretch to provide its usual traffic controlling indications, and that when an 70 75

additional indication is required to be displayed to indicate a particular traffic condition peculiar to a portion of the stretch, such apparatus then is effective to display such additional indication.

Although I have herein shown and described only a few forms of railway traffic controlling apparatus embodying my invention, it is understood that various changes and modifications may be made therein within the scope of the appended claims without departing from the spirit and scope of my invention.

Having thus described my invention, what I claim is:

1. In combination with a section of railway track having a source of energy, a plurality of circuits for connecting said source to the rails of said section, coding apparatus for coding at a distinctive rate the energy which each of said circuits transmits, means responsive to predetermined conditions for selectively rendering one or another of said circuits individually active or first one and then another of two of such plurality of circuits alternately active, and railway traffic controlling apparatus receiving energy from the rails of said section and selectively responsive to each individual coding thereof and to each alternate coding thereof.

2. In combination, section of railway track, a source of energy for the track rails of said section, coding apparatus having a plurality of circuit controlling contacts which operate at different rates, a plurality of circuits each of which includes a different one of said contacts and through which energy from said source may be supplied to the rails of said section, means for selectively rendering one or another of said circuits individually active or two of said plurality of circuits alternately active, and railway traffic controlling apparatus receiving energy from the rails of said section and selectively responsive to each individual coding thereof and to each alternate coding thereof.

3. In combination, a section of railway track, a source of energy for the track rails of said section, coding apparatus having a plurality of circuit controlling contacts which operate at different rates, a plurality of circuits each of which includes a different one of said contacts and through which energy from said source may be supplied to the rails of said section, another circuit controlling contact for said coding apparatus and operated thereby at a predetermined rate, means for selectively rendering one or another of said circuits individually active or for causing said other circuit controlling contact to render first one and then another of a selected two of said plurality of circuits alternately active, and railway traffic controlling apparatus receiving energy from the rails of said section and selectively responsive to each individual coding thereof and to each alternate coding thereof.

4. In combination, a section of railway track, a source of energy for the track rails of said section, coding apparatus having a plurality of circuit controlling contacts which operate at different rates, a plurality of circuits each of which includes a different one of said contacts and through which energy from said source may be supplied to the rails of said section, another circuit controlling contact for said coding apparatus and operated thereby at a predetermined rate, means for selectively rendering one or another of said circuits individually active or for causing said other circuit controlling contact to render a selected two of said circuits alternately active, and railway traffic controlling apparatus

receiving energy from the rails of said section and selectively responsive to each individual coding thereof and to said alternate coding thereof.

5. Apparatus for a track circuit supplied with energy coded at any one of a plurality of code rates individually or at any combination of two of such rates alternately, comprising, in combination, a code responsive relay receiving energy from said track circuit, a decoding transformer supplied with current over contacts of said code responsive relay for inducing in said transformer windings alternating current having a frequency corresponding to the code rate of operation of said code responsive relay, a code detecting relay energized from said transformer in response to alternating current of any frequency induced therein, a plurality of code selecting relays one assigned for each of said individual code rates, tuning means interposed between said transformer windings and each of said code selecting relays for conditioning each of such relays to be energized only in response to alternating current induced in said transformer having a frequency corresponding to the code rate assigned to such relay, a slow releasing repeater relay associated with each of said code selecting relays and energized when and only when the associated code selecting relay alternately picks up and releases, the railway traffic controlling apparatus selectively controlled by said code detecting relay and by said code selecting relays and by said associated slow releasing relays.

6. In combination, a track circuit supplied with energy coded at any one of a plurality of code rates individually or at any combination of two of such code rates alternately, each of said individual code rates comprising substantially equal alternate intervals of "on" and "off" periods during which current does and does not flow respectively and the individual code rates differing from each other in the number of "on" and "off" periods occurring in a given interval of time, a code responsive relay receiving energy from the rails of said track circuit, a decoding transformer supplied with current over contacts of said code responsive relay for inducing in said transformer windings alternating current having a frequency corresponding to the code rate of operation of said code responsive relay, a code detecting relay energized from said transformer in response to alternating current of any frequency induced therein, a plurality of code selecting relays one assigned for each of said individual code rates, tuning means interposed between said transformer windings and each of said code selecting relays for conditioning each of such relays to be energized only in response to alternating current induced in said transformer having a frequency corresponding to the code rate assigned to such relay, a plurality of slow releasing repeater relays one for each of said code selecting relays, means controlled by each of said code selecting relays for energizing its associated slow releasing relay when and only when such selecting relay is alternately energized and de-energized in response to operation of said code responsive relay by a combined code including the code rate of such code selecting relay, and a multiple-indication traffic controlling signal selectively controlled by said code detecting and selecting relays and by said associated slow releasing relays.

7. In combination, a section of railway track

having means for supplying to the rails thereof trackway energy coded at any one of a plurality of code rates individually or at any combination of two of such code rates alternately, code responsive means receiving energy from the rails of said section, a decoding transformer energized by said code responsive means in such manner as to cause alternating current to be induced therein having a frequency corresponding to the code rate of energy received from the track rails, a plurality of code selecting relays one for each of said individual code rates, circuit means for connecting said relays to said transformer and including means for conditioning each of said relays to be energized only in response to alternating current having a frequency corresponding to the frequency of the associated selecting relay, slow acting relays one for each of said code selecting relays, means controlled by each of said code selecting relays for energizing the associated slow acting relay whenever said code responsive relay operates in response to a combined code including the code rate associated with such code selecting relay, and a multiple-indication traffic signal selectively controlled by said code selecting relays and by said slow acting relays.

3. In combination, a section of railway track having means for supplying to the rails thereof trackway energy coded at any one of a plurality of code rates individually or at any combination of two of such code rates alternately, a code responsive relay receiving energy from the rails of said section, a plurality of code selecting relays one for each of said plurality of code rates, means controlled by said code responsive relay for selectively controlling said code selecting relays, a plurality of slow releasing relays two for each of said code selecting relays, means controlled by a front contact of each code selecting relay for energizing a first of its associated two releasing relays, means controlled by a back contact of each code selecting relay and a front contact of its associated first slow releasing relay for energizing the associated second slow releasing relay, and railway traffic controlling apparatus selectively controlled by said code selecting relays and by said associated slow releasing relays.

9. In combination, a section of railway track having means for supplying to the track rails thereof trackway energy which is coded at one or another of a plurality of code rates individually or which is formed into one or another of a plurality of distinctive code combinations each of which is constituted by repeating first one and then another of two of such plurality of code rates alternately, a code responsive track relay receiving energy from the rails of said section, a plurality of code selecting relays controlled by said track relay and each selectively responsive to a different individual code rate, a plurality of slow releasing relays two for each of said code selecting relays, means controlled by a front contact of each code selecting relay for energizing a first of its associated two slow releasing relays, means controlled by a back contact of each code selecting relay and a front contact of the associated first slow releasing relay for energizing the associated second slow releasing relay, and a multiple indication traffic controlling signal selectively controlled to different indications in accordance with the positions of said code selecting relays and of said associated slow releasing relays.

10. In combination, two adjoining sections of railway track one having means for supplying

to its track rails trackway energy coded at any one of a plurality of code rates individually or at any two of such code rates alternately, a code responsive relay receiving energy from the rails of said one section, a plurality of code selecting relays controlled by said track relay and each selectively responsive to a different individual code rate, a plurality of slow releasing relays two for each of said code selecting relays, means controlled by a front contact of each code selecting relay for energizing a first of its associated two slow releasing relays, means controlled by a back contact of each code selecting relay and a front contact of the associated first slow releasing relay for energizing the associated second slow releasing relay, and means selectively controlled by said slow releasing relays for controlling the supply of track way energy to the rails of the other of said two sections.

11. In combination, two adjoining sections of railway track one having means for supplying to its track rails energy coded at any one of a plurality of code rates individually or at any selected two of such code rates alternately, a code following track relay receiving energy from the rails of said section, a plurality of code selecting relays controlled by said track relay and each selectively responsive to said code rates, a plurality of slow releasing relays two for each of said code selecting relays, means controlled by a front contact of each code selecting relay for energizing a first of its associated two slow releasing relays, means controlled by a back contact of each code selecting relay and a front contact of the associated first slow releasing relay for energizing the associated second slow releasing relay, a traffic controlling signal associated with said section and selectively controlled by said slow releasing relays, and means also controlled by said slow releasing relays for controlling the supply of trackway energy to the rails of the other of said two sections.

12. Railway traffic controlling apparatus comprising the combination of a section of railway track, means for supplying the rails of said section with trackway energy coded at one or another of a plurality of code rates individually or at first one and then another of a selected two of such code rates alternately, means on a train for receiving a portion of said trackway energy, a code following relay responsive to the received portion of such trackway energy and operated thereby, a plurality of decoding relays controlled by said code following relay and selectively responsive to said plurality of code rates, a plurality of slow releasing relays one for each of said decoding relays and each energized when and only when the associated decoding relay is alternately picked up and released in response to the receipt of the recurrent spaced intervals of its selected code rate, and a train-carried signal selectively controlled by said decoding relays and by said associated slow releasing relays.

13. Railway traffic controlling apparatus comprising the combination of a section of railway track, means for supplying the rails of said section with trackway energy coded at any one of a plurality of different code rates individually or at any combination of a selected two of such code rates alternately, means on a train for receiving a portion of said trackway energy, a code following relay responsive to the received portion of such trackway energy and operated thereby, a plurality of decoding relays controlled by said code following relay and each selectively respon-

sive to said individual rates of coding such energy, a plurality of slow releasing relays one for each of said decoding relays and each energized when and only when the associated decoding relay is alternately picked up and released in response to the receipt of recurrent intervals of its selected code rate, a multiple-indication traffic controlling signal carried by said train and having a clear indication and a plurality of restrictive indications, a plurality of circuits controlled by said decoding relays and by said slow releasing relays, and manually operable train-carried means having a plurality of positions for selecting the particular indication to be displayed by said signal in response to the completion of one or another of said circuits, whereby each of said circuits causes one or another of said indications to be displayed according as said manually operable means is in one or another of its said positions.

14. In combination, a section of railway track, means for supplying to the rails of said section trackway energy coded at any one of a plurality of code rates individually or at any combination of two of such code rates alternately, means on a train for receiving a portion of said trackway energy, decoding means operated by the received portion of said trackway energy and selectively responsive to each individual coding thereof and to each distinctive combination of coding thereof, a multiple-indication signal carried by said train and controlled by said decoding means, and manually operable multiple-position means also carried by said train for determining the selection to be effected by said decoding means

among said signal indications whereby to cause said decoding means to be effective to control said signal to display one or another of its multiple indications for each form of trackway energy received according as said manually operable means is in one or another of its positions.

15. In combination, a section of railway track, means for supplying to the rails of said section trackway energy coded individually at one or another of a plurality of code rates or alternately at first one and then another of a particular two of such plurality of code rates, a code responsive relay operated by energy received from the trackway, a decoding transformer energized by said code responsive means in such manner as to cause the induction of alternating currents therein having a frequency corresponding to the code rate of operation of said code responsive relay, a plurality of code selecting relays one assigned for each of said plurality of individual code rates, circuit means for energizing each of said code selecting relays from said decoding transformer provided that the frequency of alternating current induced therein corresponds to the code rate assigned to such relay, a slow releasing relay for one of said decoding relays, means controlled by said one decoding relay for energizing said slow releasing relay when and only when said one decoding relay is alternately picked up and released in response to said code responsive relay following said alternate coding, and railway traffic controlling apparatus selectively controlled by said decoding relays and by said slow releasing relay.

RALPH R. KEMMERER.
